ABSTRACT

A machine for forming a tubular carton from a generally rectangular flat sidewall blank having thermoplastic coatings thereon and comprising a sidewall blank magazine, a heating station, a forming mandrel, and means for withdrawing a blank from the magazine and conveying the withdrawn blank through the heating station to the forming mandrel is improved by incorporating a hold down mechanism to maintain the position of the withdrawn blank on the conveying means, utilizing hot gas from perforated conduits to heat only the margins of the blank in the heating station, and employing a forming mandrel coated with a poly(arylene sulfide) coating composition. The forming machine can be employed in combination with a filling and sealing machine having at least one conveyor with means for properly positioning the cartons in the conveyor, means for intermittently driving the conveyor in accurately reproducible movements, filling means, means for heating the top sealing panels with hot gas, means for sealing the filled and heated cartons, and means for removing the filled and sealed carton from the conveyor. These improvements enable the machine to be operated at higher production speeds, while permitting a reduction in the size of the overall machine.

CARTON FORMING MACHINE

The invention relates to a machine for forming tubular cartons. In a specific aspect the invention relates to means for forming, filling and sealing gable top cartons.

Machines for forming tubular cartons from generally rectangular blanks generally comprise a blank supply magazine, blank heating means and at least one forming mandrel. In addition, carton forming, filling and sealing machines require filling means, score breaking means, heating means, sealing means, takeoff means, and means for conveying the cartons through each of the work stations. Difficulties with the operating speed and/or dependability in anyone of these mechanisms can limit the production rate of the entire machine.

In previous sidewall blank feeding apparatus, a mechanism such as a chip feeder or a suction cup assembly has been employed to strip an individual blank from the bottom of a stack of blanks and move it to a position where the blank could be picked up by a conveyor mechanism. When employing paperboard blanks with or without a protective coating of thermoplastic material, variations in temperature and humidity in the storage location and in the processing location affect the paperboard blanks, causing the blanks to tend to curl or bow. The use of a suction cup assembly to withdraw a blank from a magazine generally involves the bowing of the blank to move the blank past retaining elements. Deviations in the blank from a planar condition can cause the blank to be missed by the blank engaging mechanism of the conveyor and/or to come into interfering contact with machine elements, thus jamming the blank and interrupting the feeding of the blanks. Also, with chip feeders the feeding mechanism would occasionally slide past the supply magazine without engaging a blank, or only partially engage a blank thereby damaging the blank. In accordance with the present invention these difficulties can be avoided or minimized by utilizing a suction cup assembly to withdraw the blanks from the supply magazine and utilizing hold-down means which engages the blank after the blank is withdrawn from the supply magazine to properly position the withdrawn blank on the conveyor and to maintain that positioning until after the blank is engaged by the conveyor.

Difficulties have been encountered with previous means for heating the sidewall blanks. Radiant heating is slow and requires a significant portion of the machine length for continuously moving blanks and results in the heating of the entire blank rather than only the areas to be bonded. Uniform heating of the areas to be bonded is desirable for obtaining uniform bonds and cooling times and to avoid distorting stresses in the carton. In accordance with the invention these disadvantages can be avoided or minimized by utilizing conduit heaters positioned parallel to the surfaces to be heated of a blank held stationary relative to the conduit heaters during the heating operation. The uniformity of the heating can be enhanced by positioning the side margin heaters in opposite directions and by supplying hot gas to both ends of the transverse conduit heater. A cool air curtain can be established between the magazine and the heating station to avoid overheating the blanks in the magazine.

Difficulties are sometimes encountered in stripping the formed tubular carton from the mandrel due to frictional resistance between the forming surface of the mandrel and the interior surface of the carton. It is a

common practice to employ a polished steel mandrel to provide a lower frictional resistance than would be achieved with metals such as aluminum. In many of the carton forming machines employing more than one mandrel, it is customary to position the mandrels on a turret and to rotate the mandrels about the axis of the turret to move the mandrels from station to station. The use of steel mandrels on these turrets limits the practical rotative speed of the turret due to the weight of the mandrels. In accordance with the present invention the utilization of a normally solid poly(arylene sulfide) coating on the mandrel reduces the frictional resistance between the mandrel and the carton. The utilization of a normally solid poly(arylene sulfide) coating on a light weight metal such as aluminum permits the attainment of a higher production rate for carton forming machines employing a plurality of mandrels on a turret as well as providing reduced frictional resistance between the mandrel and the carton.

Accurate positioning of the carton on the conveyor which takes the cartons to the processing stations is frequently critical. Improper alignment of the cartons can result in damage to the cartons. This is particularly true for cartons which are being filled and sealed by automatic machinery. In accordance with one aspect of the present invention, the desired accurate positioning can be achieved through the use of guides and a resiliently mounted member for achieving and maintaining the position of the carton on the conveyor as the conveyor moves the carton out of the positioning station.

The motion and positioning of the conveyor in each cycle is also important. In intermittently actuated conveyors associated with machines for filling cartons with liquid material and then sealing the filled cartons, abrupt movement of the at least partially filled but unsealed containers can cause loss of product from the carton as well as improper seals resulting from the presence of liquid material on the surfaces to be bonded. Improper positioning of the carton can result in damage to the carton by interference between the improperly positioned carton and operating mechanisms of the machine. It is also common to employ a clutch with the drive mechanism, but clutches which permit variable slippage destroy the alignment relationship between the drive mechanism and the conveyor. In accordance with one aspect of the present invention these disadvantages are at least minimized, if not avoided, by utilizing a double ratchet drive mechanism wherein a resiliently mounted striker arm pivots a brake arm into engagement with the second ratchet as the reciprocating drive for the drive pawls of the first ratchet approaches the end of the forward motion. An indexing clutch can be utilized with the double ratchet drive mechanism to permit indexing of the conveyor only in proper relationship to the drive mechanism.

Hot air heater heads for gable top carton sealing machines having an inner plenum chamber which fits within the open end of the carton and two outside plenum chambers for heating portions of the outside of the carton are known. However, difficulties in achieving a liquid tight seal with this type of heater has been encountered. In accordance with one aspect of the present invention, the hot air heater comprises an annular outer plenum chamber having orifices along the length of the inner wall, with both the inner wall of the outer plenum chamber and the outer wall of the inner plenum chamber extending downwardly and out-

wardly, so that the hot air introduced into the carton is deflected upwardly out of the carton and then downwardly along the outside of the carton.

When these various operations have been performed by the filling machine, it is necessary to remove the filled container from the endless conveyor of the filling machine to permit the conveyor space occupied by the filled container to be reused in subsequent filling operations. Various methods and apparatus are known in the art for performing this function. Some, for example, use an arm or push rod to displace a filled carton from the endless conveyor of the filling machine. Another method is to dump the filled container from one conveyor to another or to displace it onto an incline and let it slide to another conveyor. While these methods are generally acceptable for the handling of filled cartons having a geometric configuration which will stabilize them against tipping or falling during handling operations subsequent to being filled, many tall containers with relatively small bases and containers made of a material which may tend to stick to a surface rather than to slide across it are difficult to push or gravity-slide from one location to another. In accordance with one aspect of the invention, each filled carton arriving at a specified station along the intermittently actuated conveyor of the filling machine is contacted by one or more suction cups, to which a vacuum has been applied, and is pulled from the conveyor of the filling machine to a desired location on a continuously actuated take-off conveyor, where the source of the vacuum to the suction cups is interrupted, releasing the carton onto the take-off conveyor.

Accordingly it is an object of the present invention to provide a new and improved machine for forming tubular cartons from generally rectangular sidewall blanks. Another object of the invention is to improve the production rate of a carton forming machine. A further object of the invention is to reduce the overall size of a carton forming, filling and sealing machine. Yet another object of the invention is to provide a new and improved carton forming, filling and sealing machine.

Other aspects, objects, and advantages of the present invention will become apparent from a study of the disclosure, the appended claims, and the drawing.

In the drawings FIG. 1 is a front elevational view of a carton forming, filling and sealing machine embodying the present invention;

FIG. 2 is a diagrammatic view in elevation of the sidewall blank feeding and heating section and the forming turret of the machine of FIG. 1;

FIG. 3 is a plan view of a sidewall blank feeder with portions of a base plate being broken out to show lower components.

FIG. 4 is a simplified elevation view along the line 4—4 of FIG. 3 showing the drive system for the feeding mechanism;

FIG. 5 is a simplified elevation view along the line 5—5 of FIG. 3 showing the vacuum cups, the hold-down bars, and the reciprocating mechanism in the down position.

FIG. 6 is a partial view in elevation along the line 6—6 of FIG. 3 showing a vacuum cup, a hold-down bar, and the associated reciprocating mechanism in the up position.

FIG. 7 is a simplified top plan view of the sidewall blank feeding and heating section of FIG. 2;

FIG. 8 is an elevational view, partly in cross section, of the transverse heater of FIG. 7; and

FIG. 9 is a simplified perspective view showing the relationship of the three heaters to the sidewall blank being heated.

FIG. 10 is a simplified elevational view of the turret structure of the machine of FIG. 1;

FIG. 11 is an exploded view, partly in cross section, of a mandrel structure suitable for use in the turret of FIG. 10;

FIG. 12 is a diagrammatic view in front elevation of the bottom blank feeding and heating subsection of the machine of FIG. 1;

FIG. 13 is a simplified side elevational view of the bottom blank heating mechanism of FIG. 12; FIG. 14 is a bottom plan view of the hot air distribution plate of one of the heater heads of FIG. 12;

FIG. 15 is a plan view of the stripping station of the turret of FIG. 10 with a carton ready to be stripped;

FIG. 16 is a plan view of the stripping station of the turret of FIG. 10 with the carton fully stripped from the mandrel;

FIG. 17 is a simplified plan view showing the layout of the two endless conveyors of the filling and sealing section of the machine of FIG. 1;

FIG. 18 is a simplified partial plan view of the mechanism for transferring cartons from the forming machine section alternately to the two endless conveyors, showing a carton being inserted into a conveyor bucket on one of the conveyors;

FIG. 19 is a fragmentary view corresponding to FIG. 18 showing the transferred carton being firmly seated in the conveyor bucket;

FIG. 20 is a perspective view of the mechanism for seating the transferred carton in the conveyor bucket;

FIG. 21 is a fragmentary elevational view of the pusher rod assembly of FIG. 18;

FIG. 22 is a simplified elevational view taken along the line 22—22 in FIG. 17, omitting several conveyor buckets for the sake of simplicity;

FIG. 23 is a simplified plan view taken along the line 23—23 in FIG. 22, showing the lower ratchet before the indexing of the conveyor;

FIG. 24 is a simplified plan view taken along the line 24—24 of FIG. 22, showing the upper ratchet before the indexing of the conveyor;

FIG. 25 is a simplified plan view taken along the line 23—23 of FIG. 22 after the lower ratchet has been indexed;

FIG. 26 is a simplified plan view taken along the line 24—24 of FIG. 22 after the upper ratchet has been indexed;

FIG. 27 is a perspective view, partly in cross-section, of the clutch mechanism of FIG. 22;

FIG. 28 is a simplified side elevation view, partly in cross section, of one of the filler units of FIG. 1, at the conclusion of one filling cycle and the commencement of a new filling cycle;

FIG. 29 is a simplified side elevational view, partly in cross section, of the filler unit of FIG. 28 shown in the position where the measuring cylinder is filled with fluid;

FIG. 30 is a simplified side elevational view, partly in cross section, of the filler unit of FIG. 28, with the filler valve lowered into the carton in the filling station;

FIG. 31 is a simplified elevational view, partly in cross section, of the filler unit of FIG. 28 showing the

measuring piston in the down position at the conclusion of the liquid discharge;

FIG. 32 is a perspective view of the adjustable lever arm for actuating the piston of the measuring and dispensing cylinder;

FIG. 33 is an alternate embodiment of the valve of the filler unit wherein the passage of the liquid from the manifold flows directly through the valve body into the measuring cylinder.

FIG. 34 is a simplified side elevational view, partly in cross section, of the score breaking mechanism of the machine of FIG. 1 in the up position;

FIG. 35 is a simplified side elevational view, partly in cross section, of the score breaking mechanism of FIG. 34 in an intermediate position;

FIG. 36 is a simplified side elevational view, partly in cross section, of the score breaking mechanism of FIG. 34 in the fully down position;

FIG. 37 is a simplified front elevational view, partly in cross section, taken along line 37-37 in FIG. 36;

FIG. 38 is a simplified plan view, partly in cross section, taken along line 38-38 of FIG. 36;

FIG. 39 is a detail elevational view of the rack and pinion mechanism for the triangular gable wings;

FIG. 40 is a detail elevational view of the mechanism for the roof panel wings;

FIG. 41 is a perspective view of the upper portion of a gable top carton before the score breaking operation; and

FIG. 42 is a perspective view of the carton of FIG. 41 after the score breaking operation.

FIG. 43 is a simplified elevational view of a carton top heating station suitable for use in the machine of FIG. 1;

FIG. 44 is a top plan view of the heater head structure for the top heating station of FIG. 43;

FIG. 45 is an elevational view in cross section taken along line 45-45 in FIG. 44;

FIG. 46 is an elevational view in cross section taken along line 46-46 in FIG. 44, omitting the container; and

FIG. 47 is a cross-sectional view taken along line 47-47 of FIG. 46.

FIG. 48 is a simplified front elevation view of the first sealing head of the machine of FIG. 1 in the up position;

FIG. 49 is a simplified front elevation view of the sealing head of FIG. 48 in the down position;

FIG. 50 is a simplified front elevation view of the second sealing head of the machine of FIG. 1 in the up position;

FIG. 51 is a simplified front elevation view of the branding head of the machine of FIG. 1 in the down or branding position;

FIG. 52 is an enlarged side elevation view of the branding head of FIG. 51 showing the actuating cam;

FIG. 53 is a simplified side elevation view along the line 53-53 of FIG. 52.

FIG. 54 is a plan view of the product discharge end of the carton-forming, filling, and sealing machine of FIG. 1;

FIG. 55 is a simplified elevational view along line 55-55 of FIG. 54; and

FIG. 56 is an elevational view illustrating the mounting of suction cups on the sub-frame.

Referring now to the drawings in detail and to FIG. 1 in particular, the carton forming, filling and sealing

machine comprises a forming section 11 and a filling and sealing section 12. The forming section 11 comprises a sidewall blank feeding and heating subsection 13, a bottom blank feeding and heating subsection 14, 5 a forming subsection 15, and a transfer subsection 16. The filling and sealing section 12 has two parallel endless conveyor systems 17, and each conveyor system comprises a filling subsection 18 occupying five conveyor stations, a defoaming station 19, a score breaking station 20, a top heating station 21, a folding and sealing station 22, a secondary sealing station 23, a branding station 24, and a transfer station 25.

The sidewall blanks 31 manually placed in the sidewall blank magazine 32 are flat, relatively stiff single 15 sheets of paperboard, rectangular in shape, scored to provide five longitudinal panels and a gable-top structure, and coated on both the top and bottom surfaces of each sheet with a thermoplastic material, e.g. polyethylene. The sidewall blanks are successively withdrawn from magazine 32 and advanced through the sidewall blank heating station 33 to the sidewall blank receiving station 34 for turret 35. At the sidewall blank heating station 33, the side margins to be overlapped and the bottom margin of the sidewall blank are heated to a bonding temperature for the thermoplastic coating.

The turret 35 is journalled on a horizontal axis and carries eight circumferentially spaced apart mandrels 36 extending radially from the axis of turret 35. The cross section of each of mandrels 36 in a plane perpendicular to its longitudinal axis is generally rectangular. Suitable drive mechanism is provided for indexing or effecting intermittent rotation of the turret 35 to move each mandrel from the sidewall blank receiving station 34 through a blank folding station 37; a bottom end closure forming, applying and sealing station 38; a secondary bottom sealing station 39; a stripping station 40; and three successive nonoperating stations 41, 42 and 43.

The tubular carton body having a bottom closure sealed thereto is removed from the mandrel 36 at the stripping station 40 and is transferred to a conveyor pocket 45 of one of the two conveyor systems 17. The 45 product to be packaged is stored in tank 49 and is introduced into the open-topped tubular carton 50 in four equal portions at stations 18a, 18b, 18d and 18e in the filling subsection 18 (See FIG. 17). If desired, any foam resulting from the filling operation can be removed at 50 defoaming station 19. The scores for the gable-top structure can be initially folded in the score breaking station 20, resulting in the conventional six-sided top structure (See FIG. 42). The gable-top ridge panels of the carton are heated in station 21 to a temperature at 55 least as high as the thermal bonding temperature of the thermoplastic coatings on the carton. The heated superstructure is then folded into contact under pressure at the folding and sealing station 22 to effect the bonding of adjacent ridge panels. Secondary sealing station 23 applies pressure to the ridge panels during cooling of the thermoplastic bond. If desired, a date indicia, plant identification or other information can be applied to the bonded ridge panels of the sealed carton at branding station 24. The formed, filled and sealed carton is removed from its conveyor pocket 45 at the transfer station 25 and placed on a delivery conveyor 60 65 46.

Referring now to FIG. 2, the turret 35 is intermittently rotated in a clockwise direction, as shown on the drawing, by suitable means, not shown. Chain 51 is driven by turret 35 and in turn drives shaft 52 to intermittently drive sidewall conveyor chains 53.

Conveyor chains 53 have dogs 54 to engage a sidewall blank 31 after it has been withdrawn from the stack to move the sidewall blank to the heater station 33 and then to the position where the blank can be engaged by the fingers 55 and moved onto the mandrel 36 in the blank receiving station 34. The heater station 33 has electrically heated hot air heater 56 which heats the upper surface of one side edge of sidewall blank 31, heater 57 which heats the lower surface of the opposite side edge of sidewall blank 31, and heater 58 which heats the upper surface of the trailing end of sidewall blank 31. An air curtain is produced by downwardly directed jets of unheated air from tube 59 when the operation of the machine is interrupted, thereby providing cooling for the sidewall blanks in the magazine 32 as a protection against damage of the sidewall blanks in the stack by excessive exposure to the hot air from heaters 56, 57, and 58.

Referring now also to FIG. 3 through 6, the supply magazine cage 32 for the storage of sidewall blanks 31 is formed by opposing side elements 61 and 62, interconnected by opposing back and front end elements 63 and 64, having vertical guide rods 65 on their topsides. A plurality of ledges 66 extend inwardly from opposing side elements 61 and 62 and opposing end elements 63 and 64 to engage marginal portions of the bottom surface of the lowermost sidewall blank 31 to support the stack of a plurality of sidewall blanks in cage 32. The magazine cage 32 is supported above the upper run of conveyor chains 53. The blank transfer means for successively withdrawing individual blanks from the magazine cage 32 and depositing the withdrawn blanks on the upper run of conveyor chains 53 comprises vacuum cups 67 and the associated mechanism. Vacuum cups 67 are mounted between conveyor chains 53. Cups 67 are reciprocated vertically through openings 68 in plate 69 to engage the bottom surface of central portions of the lowermost sidewall blank and to remove the lowermost sidewall blank 31 from the stack of sidewall blanks in cage 32 by causing the lowermost sidewall blank to bow downwardly in the center thereof, permitting the margins of the lowermost blank to move inwardly and slip past ledges 66. Vacuum cups 67 are connected to a suitable vacuum source 71. In their lower position, cups 67 are below the upper surface of plate 69 and the upper edges of conveyor chains 53 so as not to interfere with the lateral movement of a blank by conveyor chains 53.

Each vacuum cup 67 is supported by a sleeve 72 attached to a connecting bar 73 by an arm 74 (see FIG. 2). Each connecting bar 73 is attached to the upper end of the respective shaft 75, the lower end of which has a reduced diameter and is attached to bar 76 by nut 77. Shafts 75 extend through stationary bushings 78 which are mounted in bar 79. Shafts 75 can be reciprocated vertically by means of bar 76 to raise and lower suction cups 67. Bar 76 is reciprocated vertically by the drive system comprising connecting lugs 81, links 82, arms 83 and 84, and cam wheel 85 connected to a drive motor not shown. The upper ends of arms 83 have a Y-shaped yoke to receive the respective link 82, while the lower ends of arms 83 are joined by bar 86. Each link

82 is freely rotatable about pivot pins 87 and 88 mounted in lugs 81 and arms 83, respectively. Shaft 89 extends through both arms 83 and serves as the pivot pin for the rigid lever formed by arms 83 and 84 and bar 86. The lower end of arm 84 is provided with a cam follower 91 which rides in cam track 92 in cam 85. The rotation of cam 85 about the axis of shaft 93 causes the lower end of arm 84 to rise and fall in accordance with the configuration of cam track 92, thereby causing the upper ends of arms 83, and the bar 76 to move up and down. Limit switch 94, operatively connected to a solenoid valve, not shown, is activated to release the vacuum to vacuum cups 67 when reciprocal plate 76 is in the down position by the action of adjustable stop 95, mounted on bar 76, depressing plunger 96 of the limit switch 94. Conversely, a vacuum is drawn through vacuum cups 67 to remove a sidewall blank 31 from the stack of sidewall blanks when bar 76 and vacuum cups 67 are in the up position and plunger 96 is released.

Also, attached to bar 76 are a pair of U-shaped support blocks 97, each having a pivot pin 98 which extends through the sidewall of the associated sleeve 99 to allow pivotable movement of sleeve 99. The lower end of a shaft 100 is positioned within each sleeve 99 with each shaft 100 being movable vertically with respect to the associated sleeve 99. A clevis block 101 is mounted on the upper end of each shaft 100. An expansion spring 102 is mounted about shaft 100 between sleeve 99 and clevis block 101. Crank shafts 103 are rotatably mounted in sleeves 104 which are attached to the frame of the machine. Each crank shaft 103 is provided with an eccentric pin 105 which extends through the opening of the respective clevis block 101 and is rotatable therein. The pin 105 has a smaller diameter than the shaft 103, and the elongated axis of pin 105 is parallel to and spaced from the elongated axis of shaft 103. Shaft 103 extends through openings in arms 106 of yoke 107 which is secured to shaft 103 for rotation therewith. A hold-down bar 108 is attached in a horizontal position to the bottom surface of the inner end of yoke 107. In the upper position, as shown in FIG. 6, the hold-down bars 108 are under side elements 61 and 62 and out of the way of a sidewall blank 31 being withdrawn from the stack of sidewall blanks. In the lower position the hold-down bars 108 overlie the side margins of a sidewall blank 31 which has been fully retracted, as shown in FIG. 5. The eccentric mounting of pin 105 on shaft 103 permits the arcual movement of hold-down bars 108 about the elongated axis of shaft 103 in response to the vertical motion of shaft 100 and sleeve 99. Pivot pin 98 permits the pivotal motion of sleeve 99 and shaft 100 about pin 98 necessary to allow the arcuate motion of crank pin 105 and clevis block 101. Since the distance moved upwardly by bar 76 is more than the distance required for arcual movement of crank pins 105, a slot 109 is provided in each of shafts 100. A retainer pin 110 extends through sleeve 99 and slot 109 of shaft 100 to allow vertical movement of sleeve 99 relative to shaft 100.

Switch 111 is an alarm switch activated by arm 112 when the number of sidewall blanks 31 present is insufficient to permit operation of the packaging machine and is connected to a control circuit, not shown, to cause the machine to be rendered inoperative when a sufficient number of sidewall blanks is not present.

The central portion of plate 69 is supported by suitable means, for example by beam 113 and bar 79. The

outer portions of plate 69 are supported by frame members 114 and 115. Bar 79 can be supported by curved elements 116 and 117, secured to frame members 113 and 115, respectively. The frame members 114 and 115 can be secured to the angle iron frame members 118 and 119. Channel members 120 and 121 serve as guides for the upper flight of the conveyor chains 53. Details of the frame structure have been simplified or omitted for the sake of clarity of the drawings.

In operation, in the initial or starting position the chains 53 are stationary reciprocal bar 76 is in its lowermost position, hold-down bars 108 are in the down position, the stack of sidewall blanks 31 is resting on ledges 66, and plunger 96 of the valve 94 is depressed breaking the vacuum. In the down position, illustrated in FIG. 5, the spring 102 is under sufficient compression to retain the shafts 100 elevated to the extent permitted by pin 110 engaging the lower end of slot 109. As bar 76 is elevated, springs 102 maintain the shafts 100 in the elevated position with the bottom of slots 109 engaging pins 110. The upward movement of shafts 100 starts the rotative movement of the crank pins 105 to move the hold-down bars 108 from the down position to the up position. As the upward movement of bar 76 continues, the upper end of yokes 107 move against adjustable stops 122 mounted on the frame by arm 123, thereby terminating the rotation of crank pins 105 and the upward motion of shafts 100. Further upward movement of bar 76 results in relative motion of sleeves 99 with respect to shafts 100, permitted by the movement of pins 110 upwardly in slots 109. The upward movement of bar 76 terminates before pins 110 would reach the upper ends of slots 109. At the end of the upward movement of bar 76 the suction cups 67 have contacted the bottom side of the lowermost sidewall blank 31, the plunger 96 has been released to open the suction cups 67 to the reduced pressure of the vacuum source, thereby securing the lowermost sidewall blank 31 to the suction cups. The reciprocal bar 76 then begins its downward movement, permitting vacuum cups 67 to pull the bottommost sidewall blank 31 from the stack past the ledges 66 and move it downwardly into position over the upper run of chains 53 and in front of a pair of lugs 54. Although sleeves 99 move downwardly with bar 76, the compression of the springs 102 retain the hold-down bars 108 in the retracted position under elements 61 and 62 with yoke 107 against stops 122 during the initial portion of the downward movement of bar 76 and sleeves 99, the pins 110 moving downwardly in the slots 109. As the reciprocal bar 76 approaches its lowermost position with the plane of the withdrawn sidewall blank 31 being below the hold-down bars 108, the pins 110 engage the lower end of slots 109, thereby causing shafts 100 to move downwardly with the sleeves 99. The downward motion of shafts 100 causes the rotation of the hold-down bars 105 downwardly against the top edges of the withdrawn sidewall blank 31. Immediately prior to bar 76 reaching its lowermost position and after the bars 108 have started their downward rotation, the plunger 96 of limit switch 94 is contacted by adjustable stop 95, thus breaking the vacuum to the cups 67. Thus, hold-down bars 108 serve to maintain the withdrawn sidewall blank 31 in place on plate 69 after the vacuum to suction cups has been terminated, thereby assuring proper engagement of the withdrawn blank by the dogs 54. However, the downward force exerted by hold-

down bars 108 is sufficiently small to avoid interference with the forward movement of the withdrawn sidewall blank 31 by the dogs 54 of conveyor 53. After the reciprocal bar 76 reaches its lowermost position, the chains 53 are indexed and the dogs 54 push the withdrawn sidewall blank 31 laterally along the upper run of conveyor chains 53 to the heater station 33. Simultaneously, another set of dogs 54 moves the blank 31 which had been at the heater station to the position

10 where the rear edge of the heated blank is engaged by fingers 55. The fingers 55 move a previously heated blank onto the mandrel 36 in the blank receiving station of turret 35. The cycle is then repeated to move additional sidewall blanks 31 singly from cage 32 through heater station 33 and onto the mandrel 36 in the blank receiving station 34 of turret 35.

The hold-down bars 108 can be spring mounted on yokes 107, and two or more hold-down bars can be employed on each side of the blanks instead of the single bar illustrated. Cams or other suitable means could be employed to maintain the bars 108 in the retracted position until after passing of the withdrawn blank, instead of the sleeves 99, shafts 100, springs 102, and pins 110. Switch 94 can be actuated to release the blank as the blank reaches plate 69 or at any point before reaching plate 69 but after bars 108 have been rotated outwardly over the withdrawn blank. While four suction cups 67 have been illustrated, a single suction cup or any other suitable number of suction cups could be employed.

Referring now to FIGS. 2 and 7-9, the edge heater 56 comprises an electrical heater 125 having an air passage therethrough, conduit means 126 connecting the air inlet of heater 125 to a source of air under pressure, not shown, and a U shaped tube having an upper leg 127 and a lower leg 128. One end of leg 127 is connected to the hot air outlet of heater 125 and the remote end of leg 128 is closed. Leg 128 is provided with a series of orifices 129 spaced along the length of the lower surface thereof in a pattern of one or more rows of orifices which overlies the top surface of the left side margin of blank 31 in heating station 33 to direct jets of heated air against the top surface of said left margin to heat the thermoplastic coating thereon to a suitable bonding temperature. The designation of left and right are with reference to the view from magazine 32. The lower surface of leg 128 is parallel to the left side edge of blank 31 and spaced therefrom, and preferably directly overlies the margin to be heated so that the hot air jets strike the blank 31 at angles of approximately 90°, although the angle of impingement of the jets on the blank can vary from 90°. The length of the pattern of orifices 129 is preferably coextensive with the length of the side edge of blank 31.

The edge heater 57 comprises an electrical heater 130 having an air passage therethrough, conduit means 131 connected to a suitable source of air under pressure, and an L shaped conduit comprising legs 132 and 133. One end of conduit 132 is connected to the heated air outlet of heater 130 and the remote end of leg 133 is closed. Leg 133 is provided with a series of orifices 134 in the upper surface thereof in a pattern of one or more rows of orifices which is at least substantially coextensive with the length of the right side edge of blank 31 and which preferably is directly below the right side margin of blank 31 in the heating station 33, so that the jets of heated air strike the lower surface of the right

side margin to heat the thermoplastic coating thereon to a suitable temperature. The upper surface of leg 133 is at least substantially parallel to and spaced from the right side edge of blank 31. As shown in FIG. 9 the inlet to the leg 128 is at the top edge of the blank 31 while the inlet to leg 133 is at the bottom edge of blank 31. Thus the initial orifice of leg 128 is adjacent the top margin of blank 31 while the initial orifice of leg 133 is adjacent the bottom margin of blank 31. This opposite positioning of the two side heaters compensates for any drop in the temperature of the heated air occurring along the length of legs 128 and 133, thus providing a more uniform temperature along the length of the subsequently overlapped side margins.

In the presently preferred embodiment illustrated in the drawings, the transverse heater 58 comprises first and second electrical heaters 135 and 136 having the hot air outlets thereof connected to conduits 137 and 138, respectively. The remote ends of conduits 137 and 138 are joined together by partition plate 139 to provide two separate plenum chambers. The air inlets of heaters 135 and 136 are connected to a suitable source of air under pressure by conduits 140 and 141, respectively. Conduits 137 and 138 are provided with a series of orifices 142 in the lower surface thereof in a pattern of one or more rows of orifices which is at least substantially coextensive with the width of the bottom edge of blank 31, and which preferably directly overlies the top surface of the bottom margin of the blank in the heating station 33. The utilization of two heaters 135 and 136 and the partition 139 at approximately the midpoint of the width of the blank 31 minimizes the variation in the temperature to which the various portions of the bottom margin are heated. The conduits 137 and 138 are positioned with the lower surface thereof at least substantially parallel to and spaced from the bottom edge of blank 31 in the heating station 33.

A valve means 143 is positioned between conduit 144 and air tube 59. Conduit 144 is connected to a suitable means of at least substantially unheated air under pressure. Conduit 59 is provided with a series of orifices in the lower surface thereof to direct jets of cool air downwardly to form an air curtain between magazine 32 and transverse heater 58. Valve 143, which is normally closed, is actuated to the open position by suitable control means whenever the machine is energized but conveyor 53 is deactuated. This air curtain protects the blanks 31 in the magazine 32 against excessive temperatures, while avoiding the operational difficulties which would be incurred if heaters 56, 57 and 58 had to be deactuated whenever conveyor 53 became deactuated. With this system the heaters 56, 57 and 58 continue normal operation and only the blank 31 in the heating station 33 is damaged. The damaged blank can be readily removed by the operator before restarting conveyor 53.

Referring now to FIG. 10, the turret mechanism is illustrated in simplified form. In the sidewall blank receiving station 34, the blank 31 is fed into the space between mandrel 36 and the associated clamp arm 145. The clamp arm 145 is then actuated to secure the blank 31 against the mandrel 36. At the station 37, a folding mechanism (not shown) is actuated to fold the blank 31 about the mandrel 36 and to overlap and seal the free edges to form a tubular body 146. At station 38, a heated bottom blank is positioned over the outer end

of the respective mandrel 36 with the margins of the bottom blank extending laterally beyond the tubular body 146. A mechanism 147 folds the overhanging margins downwardly and then inwardly into contact with the sides of the tubular body 146 to form a carton 50 having a bottom 148 bonded to the tubular body 146. Pressure is applied to the bonded areas of bottom 148 at station 39 by apparatus not shown to maintain the bond while permitting the thermoplastic material to cool to its solidification temperature. The formed carton is stripped from the mandrel 36 at station 40 by suitable means.

Referring now to FIG. 11, the mandrel 36 comprises a base plate 149, a hollow mandrel body 150 and an end cap 151. The base plate 149 has a mounting ring 152 formed thereon which conforms to the opening 153 in the inner end of hollow mandrel body 150. The outer end of mandrel body 150 is provided with a generally rectangular recess 154, a cylindrical recess 155 and a bolt hole 156. The end cap 151 is provided with a generally rectangular projection 157 on the inner face thereof, with a secondary cylindrical projection 158 extending from generally rectangular projection 157. Projections 157 and 158 generally correspond to and fit within recesses 154 and 155, respectively, to prevent rotation of end cap 151 with respect to mandrel body 150. A bolt, not shown, extends from base plate 149 through hole 156 into the threaded opening 159 in end cap 151 to secure the end cap 151, mandrel body 150 and base plate 149 together.

Mandrel body 150 has four side faces 160, 161, 162 and 163, and end cap 151 has four corresponding side faces 164, 165, 166 and 167. When the sidewall blank 31 is positioned in station 34, the trailing (bottom) edge of the blank 31 is even with the end face of cap 151. Thus the combination of side faces 160 and 164, 161 and 165, 162 and 166, and 163 and 167 constitute the four forming surfaces of mandrel 36 for the tubular body 146. The thickness of end cap 151 is at least as great as the width of the margin of the bottom blank which is folded in overlapping relationship with the tubular body 146 so that end cap 151 serves as the anvil for the bonding operation of mechanism 147. Grooves 168 and 169 are provided in side faces 160 and 162 and extend the full length of mandrel body 150. Openings 170 and 171 in end cap 151 provided fluid communication between the end face of end cap 151 and grooves 168 and 169, respectively, so that during the removal of the carton 50 from the mandrel 36 air enters the space between the end face of cap 151 and the bottom 148 by way of grooves 168 and 169 and passageways 170 and 171. Base plate 149 is provided with bolt holes 172 for the securing of the mandrel assembly to the turret base.

In accordance with the present invention, the mandrel body 150 has a metal base 173 with the side faces 160, 161, 162 and 163 thereof being coated with a layer 174 of a normally solid poly(arylene sulfide). Any normally solid poly(arylene sulfide) can be used in the practice of this invention. The term poly(arylene sulfide) is meant to include not only homopolymers but also arylene copolymers, terpolymers, and the like, as well as blends of two or more such polymers. Poly(arylene sulfides) which are particularly suited for use in this invention are those having inherent viscosities in chloronaphthalene (0.2 gram polymer is 100 cc chloronaphthalene) at 206°C of at least about 0.08, prefera-

bly between about 0.1 and about 0.3, and more preferably between about 0.13 and 0.23. Examples of suitable polymers are disclosed, for instance, in Edmonds et al. U.S. Pat. No. 3,354,129, Nov. 21, 1967. The presently preferred polymer is poly(phenylene sulfide) made as in Example I in U.S. Pat. No. 3,354,129. Other examples of poly(arylene sulfides) are poly(4,4'-biphenylene sulfide); poly(2,4-tolylene sulfide); a copolymer from p-dichlorobenzene, 2,4-dichlorotoluene, and sodium sulfide; and blends thereof.

In addition, the poly(arylene sulfide) can be blended with other polymers, conventional additives, fillers, extenders, pigments, stabilizers, and the like. Especially preferred fillers are TiO_2 , Fe_3O_4 , and fluorocarbon polymers such as polytetrafluoroethylene. Up to about 150 parts by weight, either singly or in combination, of such fillers may be used per 100 parts by weight of poly(arylene sulfide), about 5 to 80 parts by weight being presently preferred.

In a presently preferred embodiment of the invention, titanium dioxide is mixed with the poly(arylene sulfide) at a concentration within the range of about 0.5 percent to about 100 percent by weight of titanium dioxide based on the weight of poly(arylene sulfide). More preferably, the concentration of titanium dioxide will be within the range of about 10 to about 50 weight percent based on the weight of poly(arylene sulfide). The preferred embodiment also contains from about 0.5 percent to about 75 percent by weight of a fluorocarbon polymer based on the weight of the poly(arylene sulfide). A preferred fluorocarbon polymer is polytetrafluoroethylene, and the preferred concentration thereof is in the range of about 5 to 35 percent by weight of the poly(arylene sulfide).

The coating composition can also contain from about 0.3 percent to about 4 percent by weight of a siliceous material having a particle size of less than 10 microns, preferably less than 5 microns, and more preferably less than 2 microns, including silica; silicates such as calcium silicate and magnesium silicate; aluminosilicates including artificial zeolites and clays such as bentonite, illite, montmorillonite, kaolinite, attapulgite, and talc; and combinations of these. Concentrations substantially in excess of about 4 percent by weight based on poly(arylene sulfide) have a deleterious effect on the bonding strength of the resultant coating. A siliceous material concentration within the range of about 0.4 percent to about 2 percent by weight based on the weight of poly(arylene sulfide) is presently preferred, with a concentration in the range of about 0.5 to about 1 percent by weight based on the weight of poly(arylene sulfide) being more preferred.

The substrate to be coated can be prepared by degreasing, cleaning, and drying the surface to be coated. Cleaning can be accomplished by washing or wiping with trichloroethylene, acetone, or other similar cleaners or solvents, then air drying, wiping the surface dry, or otherwise drying the surface by any suitable method.

While the poly(arylene sulfide) coating can be applied to the substrate in any manner known to the art, a preferred method is to prepare a slurry containing the poly(arylene sulfide) based coating composition, and then to spray coat the substrate with the slurry. Such a spray coating method is conducive to application of a coating of uniform thickness having a smooth, unbroken surface.

When a slurry is employed, any liquid can be used as the diluent provided the liquid is inert to the other components of the slurry and to the substrate, and provided it is readily volatilized prior to or during the subsequent

heating or curing treatment. Suitable liquids include water; light hydrocarbons having 5 to 8 carbon atoms, such as hexane, isoctane, and pentane; benzene; toluene; petroleum ether; alcohols or glycols having 1 to 4 carbon atoms, such as ethanol, propanol, i-propanol, ethylene glycol, butanol-1, and propylene glycol; or mixtures thereof. A wetting agent, usually a nonionic material such as alkylphenoxy polyethoxy alcohol, in the proportion of about 0.5 percent to about 1 percent by weight based on water can be used. Other suitable wetting agents are octylphenoxy polyethoxy ethanol, aliphatic polyethers, nonylphenylpolyethylene glycol ether, and trimethylnonyl polyethylene glycol ether. A mixture of water and propylene glycol is presently preferred. Use of a diluent containing 60 volume percent water and 40 volume percent propylene glycol has yielded excellent results. A high ratio of glycol to water prevents premature volatilization of the diluent so that boundaries can be clearly delineated and overspraying can be avoided or minimized by the ready coalescence of boundary areas.

Preparation of a suitable slurry can be accomplished in any manner known to the art. It has been found that a suitable slurry can be obtained by ball milling the poly(arylene sulfide), siliceous material, other additives, and diluent for a period of time within the range of about 2 to about 48 hours. The concentration of the polymer in the carrier liquid depends upon the particular method of coating application and whether or not additional solids are employed. As a practical matter, the slurry should not be so dilute that the polymer particles are not closely enough associated to permit them to fuse together on melting. On the other hand, the thickness of the slurry and its ease of application will impose a practical upper limit on the solids concentration. Generally, a solids content within the range of about 10 to about 60 weight percent can be used, and best results are obtained with a slurry that contains about 25 to about 40 weight percent solids based on the weight of the total slurry.

The slurry is preferably sprayed onto the substrate without prior heat treatment of the substrate, but the substrate may be heated to a temperature of at least 400° F, more preferably between about 600° and about 800° F, prior to application of the coating. If the substrate is heated prior to slurry application, it is preferably maintained at a temperature high enough to fuse the polymer on contact during the coating operation.

After the coating has been applied, the coating is cured by heating at a temperature in the range of about 500° F to about 900° F, in an oxygen-containing atmosphere, such as air, for a time in the range of about 5 minutes to about 12 hours or more. The thickness of the coating can be increased by additional applications following the same procedure after each curing. Coating thicknesses of about 0.5 to about 50 mils can easily be applied. Coatings having thicknesses of about 0.5 to about 30 mils are satisfactory for most uses.

In one particular application, the side faces 160, 161, 162 and 163 and the outer portion of the end surface of metal base 173 were coated in the following manner. The surfaces to be coated were sand blasted lightly to make the surfaces slightly rough. The roughened sur-

faces were rinsed with solvent, and the excess solvent was evaporated. The cleaned metal base 173 was heated to about 700° F and then was sprayed, while hot, with a slurry formed by admixing 800 grams of poly(phenylene sulfide), 264 grams of titanium dioxide, 19 grams bentonite, 16 grams of octyl phenoxy polyethoxy ethanol, 1657 grams of water and 1105 grams of propylene glycol. The coated base was cured in an oven for 60 minutes at 700° to 750° F. After cooling the faces and the outer portion of the end of the coated base was sprayed coated with a slurry formed by admixing 800 grams of poly(phenylene sulfide), 200 grams of titanium dioxide, 150 grams of polytetrafluoroethylene, 3200 milliliters of a 50/50 mixture of propylene glycol and water, and 32 grams of octyl phenoxy polyethoxy ethanol. The thus coated base was heated at 700°-750° F for 60 minutes to cure the second coating.

In the embodiment illustrated in FIG. 11, the metal base 173 is formed of aluminum and is fabricated in a hollow configuration to reduce the weight of the mandrel. This is particularly important for high speed operation of turret 35 where the mandrel weight is a significant factor in the stresses imposed on the machine by the intermittent rotation of turret 35 as well as the power required to initiate and terminate the rotation. In order to achieve the greater durability of steel for the operation of sealing or bonding the bottom blank to the outer margin of the tubular body 146, the end cap 151 can be made of steel. The side faces 164, 165, 166 and 167 can be polished to reduce the frictional resistance offered by the steel end cap to the stripping of the container 50 from the mandrel 36. Although the end cap 151 can also be coated with the poly(phenylene sulfide) coating composition, satisfactory results have been achieved with only faces 160, 161, 162 and 163, representing a major portion of the blank contacting surface, being coated.

Referring now to FIGS. 12-14, generally rectangular bottom blanks 175 are sequentially withdrawn from a magazine 176 by a reciprocating suction cup 177 and deposited in blank carriers 178. Carriers 178 are mounted on an endless conveyor 179, which is periodically indexed to move the bottom blank 175 to a first heating station 180, then to a second heating station 181, and finally to a transfer station 182. At each of heating stations 180 and 181 there is positioned a hot air heater head 183 which is connected by a conduit 184 to an electrical heater 185 supplied with air under pressure from a suitable osrce source by a conduit 186. Each head 183 is provided with a series of orifices 187 arranged in a pattern corresponding to the areas of blank 175 which are to be thermally bonded. Orifices 187 communicate with a central plenum chamber which is connected to conduit 184 to direct jets of heated gas against the upper surface of the area of the blank 175 which are to be bonded. The heated blank 175 is removed from its carrier 178 at the transfer station 182 and is moved to station 38 by horizontally reciprocating mechanism 188.

Referring now to FIGS. 10, 15 and 16, the stripping mechanism comprises fingers 190 and 191 mounted on carriages 192 and 193, respectively. Carriage 192 is reciprocally moved on a pair of horizontal support shafts 194 by arm 195 and linkage 196. Carriage 193 is reciprocably moved on a pair of horizontal support shafts 197 by arm 198 and linkage 199. Arms 195 and 198 are

mounted on drive shaft 200 for arcuate rotation therewith. The carriages 192 and 193 are illustrated in the forward position in FIG. 15 with a mandrel 36 carrying a carton 50 having been moved into the space between carriages 192 and 193. Upon the actuation of shaft 200, the carriages begin the rearward travel, carrying fingers 190 and 191, which clear the mandrel by a distance less than the wall thickness of carton 50, into contact with the top edge of carton 50. The continued rearward motion of carriages 192 and 193 moves the carton from mandrel 36 into the adjacent horizontal socket formed by arms 202 and 203 of transfer barrel 204, as shown in FIG. 16. Turret 204 is rotatable about a horizontal shaft in 90° increments to move the stripped carton 50 from the horizontal portion to upright position in the feeding station 205.

Additional details of a suitable construction of the turret mechanism, its drive mechanism, and the mechanisms for stations 34, 37, 38, 39 and 40 and the transfer turret 204 are disclosed in Alfred A. Barnes and Harvey H. Klein, U.S. Pat. No. 2,726,583, issued Dec. 13, 1955, which is incorporated herein in its entirety by reference.

Referring now to FIGS. 17-21, each conveyor system 17 is periodically driven by a ratchet drive 206 to move each conveyor pocket 45 from one station to the next adjacent station. Along the straight line portion of each conveyor run this distance is the distance from the centerline of one station to the centerline of the next station. The conveyor systems 17 maintain the conveyor pockets 45 stationary during the dwell period of each conveyor cycle to permit operations to be accomplished on the carton at each of the processing work stations 18a, 18b, 18d, 18e, 19, 20, 21, 22, 23, 24 and 25.

A pusher arm 207 extends vertically downwardly from the transfer arm or bar 208 and is provided with horizontally extending plates 209 and 210 to contact a side of carton 50 near the top and bottom thereof, respectively. Bar 208 is pivoted on pin 211 which is mounted on the frame of the filling and sealing section 12 for movement in a horizontal plane about pin 211. A ball 212 is mounted adjacent the free end of bar 208 and is engaged by female ball joint socket 213. Ball 212 can be mounted between arm 207 and pin 211, if desired, instead of arm 207 being between ball 212 and pin 211. A ball 214 is mounted on one end of actuating lever 215 and is engaged by female ball joint socket 216. A rod 217 connects socket 213 to socket 216. Actuating lever 215 is oscillated by power means 218 in a vertical plane about shaft 219. The oscillation of lever 215 causes rod 217 to reciprocate in a generally horizontal plane. The motion of rod 217 is nonlinear as bar 208 oscillates about pivot pin 211. The ball joints 212, 213 and 214, 216 permit the horizontal and vertical rotation of bar 217 about balls 212 and 214 necessary to accommodate the motions of lever 215 and bar 208. In FIG. 18, the carton moving mechanism is shown close to one extreme position with a carton 50 inserted into a conveyor pocket or holder 45 at the transfer station 220 of the lower conveyor. The carton 50 is illustrated in the pocket 45 in the transfer station 220 as being slightly askew. This represents an undesirable positioning which is readily corrected by the mechanism of the present invention. Further movement of lever 215 will move rod 217 upwardly, as shown in FIG. 18, to cause pusher arm 207 to travel from the transfer station 220

of the lower conveyor through feed station 205 to contact a new carton 50 and move the new carton 50 into the transfer station 220 of the upper conveyor.

A first pair of guide walls 221 and 222 are positioned between feed station 205 and the transfer station 220 of the lower conveyor 17, while a second pair of guide walls 223 and 224 are positioned between feed station 205 and the transfer station 220 of the upper conveyor 17. Guide walls 221, 222, 223 and 224 can be in the form of vertically mounted plates. Each pair of guide walls are generally parallel to each other and are spaced apart to permit a carton 50 to be moved therebetween. The guide walls can have a converging configuration adjacent the feed station 205 to insure the ease of entry of the carton 50 into the space between the guide walls. At least the major portion of each pair of the guide walls will be parallel to each other and spaced apart a distance only slightly greater than the width of carton 50 to control the alignment of the carton with the conveyor pocket 45 in the respective transfer station 220. Each pocket 45 has first and second vertical side walls 225 and 226 connected by a vertical back wall 227 in a U configuration.

The side walls 225 and 226 of each pocket 45 are at least generally parallel to each other and perpendicular to back wall 227, and are spaced apart, a distance only slightly larger than the width of carton 50.

To insure the proper positioning of carton 50 in a conveyor pocket 45, a positioning element 228 is pivotably mounted on the edge of downstream guide wall 222 which is adjacent to the lower conveyor 17, by means of hinge 229. As used herein and in the claims the term upstream and downstream are referenced to the direction of travel of the adjacent portion of the conveyor 17. Springs 230 and 231 are associated with hinge 229 to resiliently bias element 228 to a stable position which is at least substantially coplanar with plate 222. Positioning element 228 extends toward the lower conveyor 17 so that it remains in contact with the carton 50 after pusher arm 207 has inserted the carton into the pocket 45 at the transfer station 220. Upon the actuation of conveyor 17 by ratchet drive 206, the pocket 45 containing the inserted carton 50 moves out of the transfer station by going through the position illustrated in FIG. 19. The positioning element 228 is resiliently biased against carton 50 by springs 230 and 231 to firmly seat the carton 50 in the pocket 45. After the pocket 45 and its associated carton 50 move out of the transfer station 220, the carton 50 is maintained in the pocket 45 by guide 232 and the positioning element 228 clears the carton 50 and returns to its stable position to aid in guiding the next carton into the conveyor pocket 45 moving into transfer station 220. Downstream guide plate 224 for the upper conveyor is provided with a positioning element 233 which is pivotably mounted on plate 224 by hinge 234. Hinge 234 is provided with springs, not shown, corresponding to springs 230 and 231. Positioning element 233 cooperates with the upper conveyor in the same manner as element 228 does with the lower conveyor. Base plate 235, upon which plates 221 and 222 are mounted, can be provided with a central recessed portion 236 to minimize the contact between the base of carton 50 and base plate 235.

Referring now to FIGS. 22 to 26, ratchet drive 206 is supported on the main frame 237 of the filling and sealing machine by means of pillow blocks 238 and 239

and bracket 240. Rotatable shaft 241 is supported in pillow blocks 238 and 239 with the elongated axis thereof extending vertically. Ratchet housing 242 is mounted around shaft 241 between pillow block 238 and pillow block 239 and is supported on pillow block 238. Lower drive ratchet 243 is attached to shaft 241 by key 244. The lower drive ratchet 243 is driven by pawls 245 and 246 which pivot about pins 247 and 248, respectively. The arms of pawls 245 and 246 are forced inwardly towards the ratchet 243 by springs 249 and 250, respectively. Housing 242 is movable about shaft 241 by linkage 251, which is rotatable about pin 252 attached to housing 242. Clevis 253 is rotatable about pin 254, which attaches clevis 253 to linkage 251. Clevis 253 is connected to and is reciprocated by drive rod 255. Drive rod 255 is reciprocated by suitable drive means, not shown. Thus, the reciprocation of drive rod 255 first rotates the ratchet housing 242 forward in a clockwise manner, as viewed in FIG. 23, about the vertical axis of shaft 241, thereby causing the forward clockwise rotation of lower drive ratchet 243 and shaft 241 from the position shown in FIG. 23 to the position shown in FIG. 25 through the engagement of the ends of pawls 245 and 246 with the teeth 256 of ratchet 243. In the reverse motion of drive rod 255, ratchet 243 and drive shaft 241 remain stationary while the ratchet housing 242 rotates about the vertical axis of shaft 241 in a counterclockwise movement to the position illustrated in FIG. 23.

Cover plate 257 is attached to the top of ratchet housing 242. Cover plate 257 has a circular hole in the central position thereof through which shaft 241 and the hub 258 of lower ratchet 243 extends. A bracket 259 is attached to the cover plate 257 to support sleeve 260 with the central axis thereof in a horizontal position. Extending through the sleeve 260 is adjustable striker bar 261 which is biased by spring 262 against the shoulder of sleeve 260. Adjustable striker bar 261 is positioned to contact brake bar 263, which is pivotable about pin 264 of supporting bracket 265, which in turn is fixably attached to the frame 327 by support bar 240. Brake bar 263 is spring biased by tension spring 266 to a normal retracted position shown in FIG. 24, wherein the brake 263 does not contact ratchet 268. In its extended position the tooth 267 of brake bar 263 contacts a tooth 269 of upper ratchet 268 which is fixably attached to shaft 241.

The clockwise rotation of ratchet housing 242 and cover plate 257 by drive rod 255 from the position shown in FIG. 24 moves striker pin 261 into contact with the outer end of brake bar 263, causing brake bar 263 to rotate clockwise about pin 264 until the tooth 267 of brake bar 263 contacts a tooth 269 on ratchet 268. Tooth 267 of brake bar 263 contacts a tooth 269 on ratchet 268 as ratchet 268 approaches the end of the clockwise rotation. Any over travel of the conveyor sprocket drive shaft 241 which would otherwise occur due to the inertia of the conveyor chain 270, pockets 45 and cartons 50, is absorbed by spring 262. Spring 262 also serves to provide a more uniform, lower rate of deceleration for shaft 241, conveyor chain 270, pockets 45 and cartons 50. At the end of the forward travel of shaft 241 and ratchet 268, spring 262 acts through the striker bar 261 to reposition shaft 241 to its proper position before drive rod 255 starts its reverse motion to return ratchet housing 242 and the connected pawls 245 and 246 to their initial position to

begin a new drive cycle. This provides an accurate positioning of ratchets 268 and 243 and shaft 241. During the counterclockwise rotation of ratchet housing 242 and cover plate 257 by drive rod 255, striker pin 261 disengages from brake bar 263, and then spring 266 causes brake bar 263 to disengage from engagement with ratchet 268. A split collar 271 is mounted about shaft 241 immediately above ratchet 268 and is keyed to shaft 241 by key 244. A set screw 272 can be used to tighten collar 271 about shaft 241 to prevent vertical movement of collar 271 on shaft 241.

Referring now to FIGS. 22 and 27, immediately above pillow block 239 is annular flange member 273 which is mounted on bushing 274 for free rotation about shaft 241. Ring shaped sprocket 275 is fixably attached to flange member 273. Flanged member 273 has in its upper surface six radial grooves 276 located sixty degrees apart to accommodate pins 277. Pins 277 extend through lower hub member 278 and are held in place by cover plate 279. Lower hub member 278 is secured to shaft 241 by key 280, while upper hub member 281 is fixably attached to shaft 241 by threaded engagement. Spring 282 is biased between cover plate, 279 and hub member 281 to resiliently hold pins 277 in grooves 276 for driving sprocket 275 and associated flange member 273. Sprocket 275 drives chain 270 which has attached around its periphery brackets 283 fixably attached to carry conveyor pocket 45.

In operation, a 60° movement of the lower drive ratchet 243 is required to move the endless chain 270 carrying conveyor pockets 45 one position. Before indexing, the lower ratchet 243 is in the position shown in FIG. 23 and the upper ratchet 268 is in the position shown in FIG. 24. The chain 270 is accurately indexed when the reciprocating drive rod 255 moves forward, rotating the ratchet housing 242 60°, causing pawls 245 and 246 to bear against the teeth 256 of lower ratchet 243, and rotating shaft 241, upper ratchet 268, upper hub 281 and lower hub 278 sixty degrees. The rotation of lower hub 278 causes pins 277 to engage the grooves 276 of flange member 273 to drive fixably attached sprocket 275 60° and move associated chain 270 with conveyor pockets 45 one position along the path of endless conveyor 17. Accurate positioning of the conveyor is obtained when the rotation of housing 242 causes resiliently mounted striker bar 261 to strike brake pin 263, causing it to rotate about pin 264 and bear against a tooth of upper ratchet 268, stopping the shaft 241 and its associated components at the desired position. The accurate position of the conveyor 17 can be assured by adjusting the length of adjustable striker bar 261 extending through the sleeve of bracket 259. Bolts 284 extend through slots 285 in sprocket 275 to secure sprocket 275 to flange 273 and to permit adjustment of the position of sprocket 275 with respect to shaft 241. In the event the conveyor becomes jammed, a safety clutch is provided by adjusting the pressure spring 282 placed against cover plate 279 so that pins 277 can slip out of the depressions 276 of flange member 273, thereby not driving sprocket 275 when reciprocating arm 255 moves forward to rotate the housing 242. This feature also provides that the conveyor 17 will still be indexed properly once the jamming is cleared, as indexing of conveyor 17 can occur only when pins 277 are realigned with grooves 276, and this occurs drive the first time the ratchet drive is indexed after the jamming is cleared. After the reciprocating

arm 255 moves forward to index the conveyor as described above, it returns to its original position and the associated components return to their positions shown in FIGS. 23 and 24.

Referring now to FIGS. 28-32, the filling section will be described in reference to one filler unit 18a since all filler units are identical. Support 291 is connected to the main frame of the filling and sealing section 12. A cam shaft (not shown) is rotated by the main drive of the machine to reciprocate drive rods 292 and 293. Drive rod 292 has connected at its top end linkage bar 294 which is rotatable about pin 295. The other end of linkage bar 294 is connected in a pivotal relationship to lever arm 296 by pin 297. Lever arm 296 is rotatably mounted on pin 298, which is attached to support 291. The outer end of lever arm 296 is connected to the shaft 299 of valve stem 300 in a pivotal relationship around pin 301. Valve stem 300 is mounted in valve body 302 for vertical motion relative to valve body 302. The upward motion of drive rod 292 rotates lever arm 296 clockwise about pin 298 to move valve stem 300 downwardly in valve body 302, while the downward motion of drive rod 292 rotates lever arm 296 counterclockwise about pin 298 to raise the valve stem 300 with respect to the valve body 302. Valve stem 300 has an annular channel 305 around its periphery. Valve body 302 has an inlet passageway 306, which is in communication with supply conduit 307, and a second passageway 308, which is in registry with passageway 309 in meter housing 310. Supply conduit 307 is connected to the supply tank 49 (FIG. 1). Passageway 309 communicates with the metering chamber 311 in housing 310. A piston 312, provided with an O ring 313 is mounted on shaft 314 for reciprocation in the vertical direction in sealing engagement with the interior wall 315 of housing 310 so that the only entry or exit from chamber 311 is by way of passageway 309. When valve stem 300 mates with passageways 306 and 308, i.e., in the position illustrated in FIG. 28, annular channel 305 provides fluid communication from supply conduit 307 to metering chamber 311. A plug 316 can be used to close off the outer end of passageway 309 when this passageway is bored all the way through housing 310 for the purpose of ease in cleaning. Valve stem 300 has an interior chamber 317 and an inclined passageway 318 that connects the interior chamber 317 with passageway 308 when the valve stem 300 is in the discharge position shown in FIG. 30. At its lower end valve stem 300 has a plurality of passages 319 which connect the interior chamber 317 to a plurality of discharge ports 320 for discharge of milk or other fluid when the valve stem 300 is in the discharge position as shown in FIG. 30. A plug 321 having a conically shaped top 322 mounted on base 323 fits into the lower end of valve stem 300, sealing the interior chamber 317 from leakage, but providing easy access to the interior of valve stem 300 for cleaning. Base 323 has a ring shaped gasket 324 in groove 325 to provide a liquid tight relationship between the cylindrical base 323 and the interior wall of valve stem 300. Plug 321 is retained in valve stem 300 by retainer 326.

Attached to the upper end of drive rod 293 is linkage bar 327 which is pivotably attached to drive rod 293 by pin 328. Linkage bar 327 is pivotably attached at its upper end to one end of lever arm 329 by pin 330. Lever arm 329 is pivotable about fixed pin 331, which is attached to support 291. At its outer end lever arm

329 is pivotably attached to piston rod 314 by pin 332. Plate 333 is pivotable about bolt 334, which is attached to lever arm 329. Plate 333 has a notch 335 which fits over pin 332 to provide a quick disconnect for the piston rod 314. The upward motion of drive rod 293 causes the clockwise rotation of lever arm 329 about pin 331 forcing shaft 314 and piston 312 downwardly, while the downward motion of drive rod 293 causes a counterclockwise rotation of lever arm 329 about pin 331 forcing shaft 314 and piston 312 upwardly.

Referring now to FIG. 32, the stroke of piston 314 in metering housing 310 can be easily adjusted by varying the distance between pins 330 and 331 by moving the position of the sliding bar element 329a of lever arm 329 in the channel element 329b of lever arm 329. This adjustment is made by rotating lever arm 336 which is pivotably attached at approximately its center to bar element 329a by bolt 337. Lever arm 336 has at its upper end a groove 338 into which pin 339, extending from channel element 329b, fits. Bolts 340 fit through slots 341 in bar 329a into channel element 329b to lock the components in position. The stroke of the piston rod 314 and piston 312 in metering housing 310 can thus be varied by changing the effective length of the lever arm 329 connected to the drive rod 293. Minute adjustments of milk volume or other liquids discharged from each filler unit may thus be made.

At the start of a new filling cycle, the components are in the position shown in FIG. 28 wherein a carton 50 is presented underneath the filler unit 18a for filling, piston 312 is in the down position, and valve stem 300 is in the up or closed position, preventing flow from the metering chamber 311 into the carton 50, but permitting the flow of milk from conduit 307 through passageways 306, 305, 308, and 309 into chamber 311. A downward movement of drive rod 293 causes an upward movement of the outer end of lever arm 329, raising piston rod 314 and piston 312 in metering housing 310 until chamber 311 reaches the desired volume. Additional rotation of the cam shaft, not shown, causes upward movement of drive rod 292 and a downward movement of the outer end of lever arm 296 moving valve stem 300 downwardly so that its lower end and discharge ports 320 are projected inside the carton 50 to be filled. This movement of valve stem 300 in a downward position also connects passageway 318 to passageway 308 and the interior chamber 311 of metering housing 310. In this position valve stem 318 also seals off supply conduit 307 and passageway 306 from metering chamber 311 by the downward movement of valve stem 300 moving passageway 305 out of registry with passageways 306 and 308. See FIG. 30. Now referring to FIG. 31, further rotation of the cam shaft, not shown, causes an upward movement of drive rod 293 and a downward movement of the outward end of lever arm 329 to push piston rod 314 and piston 312 to the bottom of measuring cylinder in housing 310, displacing the milk within metering chamber 311, causing it to flow to passageways 308 and 318 into the interior 317 of valve stem 300 and then through passageways 319 and out discharge ports 320 into the milk carton 50. Now referring again to FIG. 28, further rotation of the cam shaft causes a downward movement of drive rod 292 and an upward movement of the outer end of lever arm 296 to raise valve stem 300 back to its closed position and again connecting supply conduit 307 and passageway 306 to passageway 308 through annular chan-

nel 305. Retainer 326 is preferably a quick disconnect device such as a bayonet joint, so that plug 321 can be readily removed for cleaning. Valve body 302 and valve stem 300, apart from plug 321 and the O-rings, 5 are preferably fabricated as single unitary elements for simplicity in manufacturing and cleaning.

In another embodiment shown in FIG. 33, the interior 317' of valve stem 300' is connected to the passageway 306' and passageway 308' by openings 342 and 343 in valve stem 300'. Openings 342 and 343 thus allow milk to flow from supply conduit 307 into the interior 317' of valve stem 300' during the upward movement of piston 312 in metering housing 310. The milk remaining in the interior 317' of valve stem 300' becomes part of the measured volume of milk to be discharged into the carton 50.

Referring now to FIGS. 34-40, the score breaking mechanism 20 has a support frame 351 having a base 352 mounted on the frame of the carton filling and sealing machine section 12 above a cam shaft, not shown. Push rod 353 is reciprocated through support 354 by the cam shaft. Push rod 353 is connected to shaft 355 through adjustable linkage 356 for reciprocation of shaft 355 to drive a pair of score breaker mechanisms 20, one on each side of support 351. Only one score breaker mechanism 20 is shown since both are identical. Clevis 357 is mounted on the upper end of shaft 353 and is pivotably connected to crank arm 358 through pin 359. Crank arm 358 is fixedly connected to shaft 360 which is pivotably mounted in support 351. Also affixed to shaft 360 is lever arm 361, which has at the opposite end thereof clevis 362 which is connected in pivotal relationship to linkage 363 by pin 364. The arcuate movement of lever arm 361 causes linkage 363, connected to clevis 365 by pin 366, to vertically reciprocate the drive push rod for the left score breaker mechanism, not shown. Linkage 367 is connected in pivotal relationship to both lever arm 361 and linkage bar 368. Linkage bar 368 is pivotable about pin 369, supported in frame 351. The opposite end of linkage bar 368 is pivotably connected to U-shaped arm 370 by pin 371. The opposite end of U-shaped bar 370 is connected to clevis 365 of the right score breaker by pin 366 to drive push rod 372. The reciprocation of shaft 355 through the linkage heretofore described will reciprocably drive the push rods 372 of the two score breaker mechanisms in an identical manner.

Carriage 373 is slidable to a limited extent on push rod 372 by virtue of the bias provided by spring 374 against the lower shoulder 375 of clevis 365 and the top of carriage 373, forcing carriage 373 against stop 376 at the lower end of push rod 372. Carriage 373 is supported by plate 377 which guides the movement of carriage 373 by being slidable in the ways 378 of the main frame of the filling and sealing machine section 12 (see FIG. 38).

Support 379 is attached to the front end of carriage 373 and plate 380 is secured to the lower outward edge of support 379. Attached to the inner surface of plate 380 are gable wing supports 381. A rotatable shaft 382 is horizontally mounted in supports 381. A pinion gear 383 and a triangular gable wing 384 are mounted on shaft 382 for rotation therewith. A shaft 385 having a gear rack 386 on the lower end thereof is mounted in one of supports 381 for reciprocal movement in a vertical direction with the gear rack 386 engaging pinion gear 383. A spring 387 is mounted about shaft 385 and

extends from a shoulder 388 on the upper end of gear rack 386 to a shoulder 389 of support 381 to bias the rack 386 to the downwardly extended position. Gable wing 384 rotates about shaft 382 inwardly toward the carton 50 during the downward movement of the carriage 373 after the rack 386 contacts stationary stop 390 attached to the frame of the machine by element 391, causing the relative movement between rack 386 and carriage 373 to drive pinion gear 383.

A rotatable shaft 392 is horizontally mounted in carriage 373 opposite shaft 382. A pinion gear, not shown, is mounted on shaft 392 for rotation therewith. A shaft 393 is mounted in carriage 373 for reciprocating movement in a vertical direction. Gear rack 394 is mounted on the lower end of shaft 393 and is engaged by the pinion gear. A spring 395 is mounted about shaft 393 and extends between shoulders 396 and 397 to bias the rack 394 to the downwardly extended position. Gable wing 398 is mounted on shaft 392 for rotation therewith inwardly toward the carton 50 during the downward movement of carriage 373 after rack 394 contacts stationary stop 399, attached to frame 351. Thus the mechanisms for operating gable wings 384 and 398 are essentially identical.

Push rod 372 has a large diameter portion 401 and a small diameter portion 402 separated by shoulder 403. The large diameter portion 401 extends into opening 404 of carriage 373. Fixedly attached against the shoulder 403 of push rod 372 is gear rack 405 (see FIG. 40) which engages pinion gears 406 and 407. Roof panel wing 408 and pinion gear 406 are fixedly attached to shaft 409 for rotation therewith. Roof panel wing 410 and pinion gear 407 are fixedly attached to shaft 411 for rotation therewith. Reciprocal movement of the gear rack 405 in a vertical direction causes the arcuate motion of roof panel wings 408 and 410 simultaneously about the shafts 409 and 411, respectively. During the downward movement of push rod 372, carriage 373 and associated components are moved downwardly to engage a carton 50 held in score breaking position by conveyor 17. The racks 386 and 394 first contact the stops 390 and 399, respectively. Additional downward movement of the carriage 373 causes the gable wings 384 and 398 to fold inwardly against the end panels of the carton before the roof panel wings 408 and 410 begin their movement. Additional downward movement of the carriage 373 causes the slide plate 377 to contact stop 412 attached to support 351, stopping the movement of carriage 373. Since the push rod 372 is slidable within carriage 373 against the bias of spring 374, further movement of the push rod 372 within carriage 373 causes rack 405 to rotate pinion gears 406 and 407, folding roof panel wings 408 and 410 inwardly against the roof panels of the carton to complete the score breaking (see FIGS. 36, 38 and 42). The subsequent upward movement of push rod 372 caused by the reciprocation of shaft 355 and its associated linkage initially causes the roof panel wings 408 and 410 to fold outwardly and then causes the carriage 373 to begin its upward movement as soon as stop 376 contacts the bottom of carriage 373. The upward motion of carriage 373 permits springs 387 and 395 to move racks 386 and 394 downwardly with respect to carriage 373, thereby rotating shafts 382 and 392 to reTRACTING gable wings 384 and 398 to the vertical position.

Referring now to FIGS. 41 and 42, the carton 50 has vertical score lines 415, 416, 417, and 418 to form the four vertical sides of the carton. A series of horizontal score lines 419, 420, 421 and 422 form the bottom of the gable-top structure, while a second series of horizontal score lines 423, 424, 425 and 426 form the bottom of the six ridge panels 427, 428, 429, 430, 431 and 432. Score lines 415, 416, 420 and 424 define one roof panel 433, while score lines 417, 418, 422 and 426 define the opposite roof panel 434. Score line 435 divides ridge panels 427 and 428, while score line 436 divides ridge panels 430 and 431. Score line 437 extends from the intersection of score lines 415 and 419 to the intersection of score lines 435 and 423, while score line 438 extends from the intersection of score lines 418 and 419 to the intersection of score lines 435 and 423, to form the three triangular panels 439, 440 and 441. Similarly, score line 442 extends from the intersection of score lines 416 and 421 to the intersection of score lines 425 and 436 while the score line 443 extends from the intersection of score lines 417 and 421 to the intersection of score lines 425 and 436, to form the three triangular panels 444, 445 and 446.

In operation, a carton 50 carried by conveyor 17 is positioned underneath the score breaker mechanism 20. The carriage 373 is initially in the up position, as shown in FIG. 34. The initial downward motion of the push rod 353 causes adjustable link 356 and shaft 355 to move downwardly, rotating crank 358 in a counter-clockwise direction along with lever arm 361, causing a downward movement of link 367 and a clockwise rotation of lever bar 368. The clockwise rotation of lever bar 368 moves U-shaped bar 370 downwardly, driving push rod 372 downwardly. The downward movement of push rod 372 moves carriage 373 downwardly. As carriage 373 moves downwardly, bringing the gable panel wings 384 and 398 and the roof panel wings 408 and 410 into close proximity to the top of the carton 50, rack 386 contacts the stop 390. Additional downward movement of the carriage 373 causes racks 386 and 394 to drive gable panel wings 384 and 398 inwardly against the panels 440 and 445, breaking the score lines 419, 421, 435, 436, 437, 438, 442 and 443. When the carriage 373 has reached the lower limit of its travel by contacting stop 412, the push rod 372 continues its downward movement against the bias of spring 374 pushing rack 405 downwardly to drive pinion gears 406 and 407 and the associated roof panel wings 408 and 410 against the roof panels 433 and 434, breaking score lines 420 and 422, and folding the roof panels 433 and 434 inwardly over the already enfolded gable ends. At this point all the components have reached the lower limit of their travel (see FIGS. 36 and 38). Further rotation of the cam shaft, not shown, causes an upward travel of the shaft 355, and associated linkage to move push rod 372 upwardly. The initial upward movement of push rod 372 reverses the procedure heretofore described by permitting rack 405 to move upwardly to drive pinion gears 406 and 407 to move the associated roof panel wings 408 and 410 outwardly. Further upward movement of the push rod 372 causes stop 376 to contact carriage 373, moving carriage 373 upwardly and allowing the racks 386 and 394 to move downwardly due to the bias of springs 387 and 395. As the racks 386 and 394 move away from stops 390 and 399, the gable panel wings 384 and 398 move outwardly away from the carton 50. As the push rod

372 and the carriage 373 continue their upward movement to their upper limit as shown in FIG. 34, the scorebroken carton 50 is cleared for movement to the sealing station by conveyor 17. Another carton moves into position underneath the score breaker, and the cycle is repeated.

Referring now to FIGS. 43-47, a filled container 50, having had the gable-top score lines broken so that the six ridge panels have assumed the six sided configuration illustrated in FIG. 42, is positioned in its conveyor pocket 45 at the top heating station 21. The heater head 452 for heating the ridge panels is shown in the down position, encompassing the ridge panels of the gable-top structure of container 50. Air under pressure is supplied through conduit 453 to the inlet of electrical heater 454. The heated air passes through conduit 455 to the inlet of heater head 452. While air is the presently preferred heating gas, other gases may be employed instead of air.

The heater head 452 comprises a horizontal base plate 461 to which cylindrical bar 462 and vertical plates 463, 464 and 465 are secured by suitable means, for example by welding. The upper portion of bar 462 has a large diameter bore 466 formed therein to receive the heated air from heater 454. The upper end of bar 462 is provided with external threads 467 to facilitate the connection thereof to conduit 455. A secondary central base plate 468 having a six-sided configuration corresponding to and slightly smaller than the six-sided configuration of the ridge panels of the gable-top structure is secured to the lower side of the central portion of base plate 461. An outer secondary base plate 469 having a six-sided opening therein corresponding to and slightly larger than the six-sided configuration of the ridge panels is secured to the periphery of base plate 461 to form a continuous channel 471 between central plate 468 and outer plate 469 adapted to receive the upper edge of the ridge panels of the container 50. If desired, channel 471 can be omitted, and plates 468 and 469 can be formed as a single element. Plates 468 and 469 can also be formed with plate 461 as a single piece. A central plenum chamber 472 is formed by bottom wall 473 and sidewall sections 474, 475, 476, 477, 478 and 479, together with secondary central base plate 468. A passageway 480 extends through the lower portion of rod 462, base plate 461 and secondary central base plate 468 to provide fluid communication between bore 466 and plenum chamber 472. An outer annular plenum chamber comprising first and second compartments 481 and 482 is formed by outer wall sections 483, 484, 485 and 486, inner wall sections 487, 488, 489, 490, 491, and 492, together with secondary outer base plate 469, and bottom walls 495 and 496. In one embodiment the outer annular chamber is divided into two separate compartments by partitions 493 and 494. A passageway 497 extends through rod 462, plate 463, and base plate 461 into opening 498 in secondary outer base plate 469 to provide fluid communication between bore 466 and compartment 481. A passageway 499 extends through rod 462, plate 464, and base plate 461 into opening 501 in secondary outer base plate 469 to provide fluid communication between bore 466 and compartment 482.

The continuous outer sidewall of the central plenum chamber 472 formed by sidewall sections 474, 475, 476, 477, 478 and 479 corresponds to the six-sided

opening formed by the six ridge panels of the container 50, but is slightly smaller in dimensions so that the central plenum chamber 472 can enter the carton opening without contact between the carton and the heater head 452 occurring. Sidewall sections 475 and 478 extend along horizontal lines parallel to each other and to the horizontal lines of the ridge panels surmounting the roof panels of the gable top structure of carton 50. Sidewall sections 474 and 479 are joined together between one end of section 475 and the adjacent end of section 478 to form a V having the apex thereof directed toward the central vertical axis of the carton 50 being heated. Similarly, sidewall sections 476 and 477 are joined together between the other adjacent pair of ends of sections 475 and 478 to form a second V having the apex thereof directed toward the central vertical axis of the carton 50 being heated. The sidewall sections 474, 475, 477, 478 and 479 are inclined to the vertical so that they extend downwardly from secondary central base plate 468 and outwardly away from the central vertical axis of container 50 and heater head 452. An angle of inclination to the vertical for sections 474-479 in the range of about 10° to about 30° is satisfactory, with an angle of inclination in the range of about 150° to about 25° being preferred.

The outer wall of the central plenum chamber 472 is provided with perforations 502 therethrough spaced at intervals along the length of each of the six sidewall sections 474-479 for directing jets of heated air at the inner surface of each of the six ridge panels of the carton 50 being heated. The inclination of the outer sidewall formed by section 474-479 and the inclination of the inner surface of the ridge panels of carton 50 are such that the jets of heated gas strike the inner surface of the ridge panels at acute angles and are deflected upwardly out of the carton 50. The upward direction of these jets minimizes the heating of the product being package in carton 50. The upward flow of the heated gas along the inside surface of the ridge panels aids in cleaning the inner surface of the ridge panels of any particles or droplets of the material being packaged, thereby minimizing defective sealing of the ridge panels due to the presence of material which would interfere with the effectiveness of the seal. The heated air escapes from the interior of the carton 50 by moving upwardly through the space between the outer sidewall of plenum chamber 472 and the carton ridge panels.

The continuous inner wall of the outer plenum chamber formed by the six sidewall sections 487, 488, 489, 490, 491 and 492 also corresponds to the six sided opening formed by the six ridge panels of the container 50, but is slightly larger in dimensions so that the inner wall of the outer plenum chamber and the outer wall of the inner plenum chamber 472 form an annular space into which the ridge panels of the carton 50 can extend without contacting the heater 452. The sidewall sections 488 and 486 extend along horizontal lines parallel to the horizontal lines of sidewall sections 475 and 478. Sections 487 and 492 are joined together between one pair of adjacent ends of sections 486 and 488 to form a V having the apex thereof directed toward the central vertical axis of the carton 50 being heated. Similarly, sidewall sections 489 and 490 are joined together between the other pair of adjacent ends of sections 486 and 488 to form a V having the apex thereof directed toward the central vertical axis of carton 50. Sidewall sections 483, 484, 486, 487, 488, 491 and 492 form a

generally triangular chamber 481 having parallel wing chambers extending from opposite ends thereof. Similarly sidewall sections 484, 485, 486, 488, 489, 490 and 491 form a second generally triangular chamber 482 having parallel wing chambers extending from the opposite corners. This configuration is advantageous in the distribution of the heated gas to the various perforations.

The sidewall sections 487-492 are inclined to the vertical so that they extend downwardly from secondary base plate 469 and outwardly away from the central vertical axis of container 50 and heater head 452. The angle of inclination to the vertical for the sidewall sections 487-492 will generally be in the range of about 50° to about 50° and preferably will be in the range of about 15° to about 30°. The inner wall of the annular plenum chamber 481, 482 is provided with perforations 503 therethrough spaced at intervals along the length of each of the six sidewall sections 487-492 for directed jets of heated gas at the outer surface of each of the six ridge panels of the carton 50 being heated. These jets strike the outer surface of the ridge panels at acute angles and are deflected downwardly away from the top edge of the carton 50. The downward flow of heated gas along the outer surface of the ridge panels cleans this surface of any foreign material such as particles or droplets of the material being packaged. This cleaning action is very advantageous in the formation of the bond between the outside surfaces of the pair of adjacent ridge panels over each enfolded portion of the gable structure. Heating the outside surfaces of all of the ridge panels gives a more uniform temperature of the coated surfaces to be bonded and reduces the time required for heating. Directing jets of heated gas at the external surface of all of the ridge panels also avoids deformation of the open end of the carton due to uneven pressures, thereby minimizing the possibility of contact between the carton and the heater head.

The bracket 504 is secured to flange 465 by suitable means. Bracket 504 is provided with a plate 505 which fits within a guideway to provide horizontal stability of the heater head 452 as it is vertically reciprocated. Suitable linkage means, not shown, connects bracket 504 to the drive mechanism of the machine to lower heating head 451 to enclose the ridge panels of a carton after the carton has been indexed to top heating station 21. After the thermoplastic coatings on the ridge panels are heated to a tacky condition, bracket 504 is powered to raise the heating head 452, permitting the heated carton to be indexed to sealing station 22.

Now referring to FIGS. 48 and 49, the supporting framework 511 is mounted to the frame of the machine by bolts 512 and supports the first sealing mechanism 22 above the conveyor 17 (shown in FIG. 17 and omitted from FIGS. 48-51 for sake of simplicity). When a carton 50 is presented under the first sealing head mechanism 22 as shown in FIG. 48, it has been filled with the liquid to be packaged at stations 18a, 18b, 18d and 18e, scorebroken at station 20 to the configuration shown in FIG. 42, and the top sealing surfaces heated to bonding temperature at station 21. Sealing jaws 513 and 514 are shown in the up and open position in FIG. 48 and in the down and closed position in FIG. 49. Sealing jaws 513 and 514 have first generally planar surfaces 515 and 516, respectively, which are inclined to the horizontal reference in the down position at substantially the same angles as the corresponding roof

panels 433 and 434 of the sealed carton 50. Sealing jaws 513 and 514 have second generally planar surface 517 and 518, respectively, which extend at least generally vertically when jaws 513 and 514 are in the fully down and closed position. Surfaces 517 and 518 can have raised areas to create points of high pressure in the sealed ridge panels of carton 50. Jaw 513 is mounted on the lower end of lever arm 519, while jaw 514 is mounted on the lower end of lever arm 520. Lever arms 519 and 520 are pivotably mounted on carriage 521 at locations adjacent their lower ends by bar 522 and pivot pin 523 and 524. Spring 525 is attached to lever arms 519 and 520 at locations adjacent their upper end. A cam follower 526 is mounted on the upper end of lever arm 519 by pin 527, and a cam follower 528 is similarly mounted on the upper end of lever arm 520 by pin 529. Cam follower 526 and 528 are retained in contact with the camming surfaces of cam 530 by the action of spring 525. Cam 530 is mounted on the lower side of bar 531, which in turn is connected to clevis 532. Bar 531 is mounted on shafts 533 and 534 for vertical movement relative to carriage 521. Shafts 533 and 534 are mounted in supports 508 and 509 which are secured to carriage 521. Bar 531 is movable vertically on shafts 533 and 534. Springs 510 are mounted on shafts 533 and 534 between bar 531 and support 509 so that downward motion of bar 531 on shafts 533 and 534 compresses the springs 510. A drive rod 535 is pivotably connected to clevis 532 by pin 536, so that downward movement of rod 535 pushes cam 530 downwardly against cam followers 526 and 528, moving the carriage 521 downwardly until carriage 521 contacts stops 537. During this initial downward motion, the sloped surfaces 515 and 516 contact the upper edges of the ridge panels 429 and 432, forcing the roof panels 433 and 434 inwardly until ridge panels 439 and 432 contact each other. The carriage 521 stops, but drive rod 535 continues downwardly, moving bar 531 relative to shafts 533 and 534 and carriage 521, thereby compressing springs 510 and forcing cam 530 between cam followers 526 and 528, rotating lever arms 519 and 520 about pins 523 and 524 to move the vertical surfaces 517 and 518 of jaws 513 and 514 toward each other to firmly bond the heated carton ridge panels together. When drive bar 535 starts its upward motion, bar 531 travels upwardly with respect to shafts 533 and 534 due to the compression of springs 510, opening jaws 515 and 516. After cam 530 is withdrawn from the extended position between cam followers 526 and 528, bar 531 contacts support 508, so that the continued upward movement of shaft 535 also raises carriage 521. Referring now to FIG. 50, the mechanism of the second sealing head 23 is essentially identical to that of the first sealing head 22 except for the shape of sealing jaws 513a, 514a, and the identical elements are identified with primed reference numbers in FIG. 50. Since the carton 50 is already sealed when it reaches the second sealing head mechanism 23, the jaws 513a and 514a do not have the extended inclined surfaces. Otherwise, the second sealing head mechanism 23 operates in the same manner as the first sealing head mechanism 22. The sealing jaws 513, 514, 513a and 514a are cooled with tap water. The cooling water lines have been omitted from the drawing for the sake of clarity. However, the water enters port 538 in jaw 513, passes from port 539 of jaw 513 to port 540 of jaw 513a, from port 541 of jaw 513a to port 542 of jaw 514, from port 543 of

jaw 514 to port 544 of jaw 514a, and exits from port 545 of jaw 514a.

Referring now to FIGS. 51-53, the branding head support 550 is attached to the frame of the machine by the bolts 551. Branding head 552 is mounted on the lower ends of vertical shafts 553 and 554, which are reciprocable through collars 555 and 556 fixably attached to plate 557 of support 550. Shafts 553 and 554 have at their upper ends the stop collars 558 and 559 to limit the downward movement of branding head 552. The reciprocable movement of branding head 552 is caused by the reciprocable movement of drive shaft 560, connected to the upper plate 561 of branding head 552 and extending through an opening in support plate 557. Branding head 552 is biased in the upward direction by the tension of spring 562. Shaft 560 is driven by suitable linkage attached to the main drive mechanism of the machine.

The branding head 552 has a front support plate 563 and a back support plate 564, both being attached to support 550. Printing head 565 and anvil head 566 are pivotable about pins 567 and 568 supported in plates 563 and 564. In the upper portions thereof, the printing head 565 and the anvil head 566 have cam followers 569 and 570 which contact cam 571 attached to the lower end of shaft 560. Spring 572 is attached between pins 573 and 574 to bias printing head 565 and anvil head 566 to the open position. At its lower end anvil head 565 has anvil surface 575 which contacts the backside of the ridge panel structure during the printing on the front side of the ridge panel structure by the printing head 565. Printing head 565 has in its lower portion type holder 576 holding a plurality of type letters or numbers 577. Type holder 576 is maintained in the branding position by holding bracket 578 which is held in place on the bottom of printing head 565 by screw 597 and bias spring 580 and by swingout arm 581. Arm 581 is held in the position shown in FIG. 53 by the bias of spring 582. Swingout arm 581 has in its lower end a threaded shaft 583 which extends into recessed hole 584 and is adjustable in length by nuts 585 to hold the type holder 576 in position. The upper end of swingout arm 581 is mounted on shaft 586 and is movable inwardly against the bias of spring 582 along shaft 586. Nuts 587 adjust the normal or outermost position of arm 581 on shaft 586. Swingout arm 581 provides a means for quick change of the data to be printed on the milk carton. The upper end of swingout arm 581 can be pushed inwardly against spring 582, permitting the lower end of swingout arm 581 and shaft 583 to move outwardly so that the arm 581 can be rotated about shaft 580 in a clockwise direction, as viewed in FIG. 52, permitting the removal of type holder 576 and its associated type 577. Another type holder 576 can be quickly inserted by reversing the procedure. Immediately above type holder 576 in printing head 565 is electrical heater 588, which can be adjusted to provide sufficient heat for branding the desired data into the ridge panel structure of the milk carton 50.

In operation, when a carton is presented to the branding head by the indexing of the conveyor 17, shaft 560 is moved downwardly, placing spring 562 under tension. Further downward movement of shaft 560 causes the head 552 to reach the limit of its downward movement allowed by the stops 558 and 559. The continued downward movement of shaft 560 causes cam

571 contacting cam followers 569 and 570 to spread apart the upper ends of printing head 565 and anvil head 566, pivoting them about the pins 589 and 590, and causing type 577 and anvil surface 575 to contact 5 the carton 50 to print the desired information. At this point the cam 571 has reached the lower end of its downward movement and begins its upward travel, causing the printing head 565 and anvil head 566 to 10 pivot inwardly at the top due to the bias of spring 572, thereby opening the branding head to release the carton 50. As the cam 571 reaches the upper limit of its movement, the spring 562 causes the branding head 552 to move upwardly to its original position.

Referring now to FIGS. 54-56, the endless intermittently actuated conveyors 17 deliver filled and sealed cartons 50 to transfer stations 25a and 25b using conveyor pocket 45 to intermittently slide the cartons 50 along flat rails 594. Endless conveyors 17 are incrementally indexed in a manner such that two filled and 15 sealed cartons 50 in conveyor pockets 45 are simultaneously advanced to transfer stations 25a and 25b during the advance portion of the conveyor cycle. The conveyor pockets 45 carrying the advanced cartons 50 remain at transfer stations 25a and 25b during the dwell 20 portion of the conveyor cycle, after which the cycle repeats itself, advancing two more containers 50 the incremental distance to transfer stations 25a and 25b. The conveyors 17 and other major components of the transfer mechanism 25 are supported on the frame 595 25 of the carton-forming and filling machine.

Conveyor pockets 45 comprise two vertical side plates 225 and 226 connected at angles of nominally 90° to a third vertical back plate 227, the vertical back plate 227 being applied to the drive means of the respective conveyor 17. The U-shaped configuration of conveyor pocket 45 accurately maintains each container 50 at its proper location along the respective conveyor 17 but also makes it necessary to remove a container from the pocket which has carried it to transfer station 25a or 25b drawing the container away from the back plate 227 of the pocket in a vertical direction or a horizontal direction perpendicular to the back 227, or in a combination of such vertical and horizontal directions. The configuration of the conveyor pockets 45 negates the use of any removal technique involving displacement of the filled container 50 in a lateral direction parallel to the surface of the conveyor pocket back plate 227.

Flat rails 594 are positioned directly below the line 30 of travel followed by conveyor pockets 45 and are of sufficient width that the entire bottom surface of each container 50 can rest upon the rail 594 during the dwell portion of the operation of intermittent conveyors 17 and slide along the rail 594 during the moving portion 35 of the conveyor operation. The top surfaces of both flat rails 594 are substantially in the same horizontal plane while the upper surface of conveyor 46 is preferably slightly below the plane of rails 594. Transfer stations 25a and 25b are preferably located so that a straight delivery conveyor 46 will be tangent to both rails 594 at transfer stations 25a and 25b.

Sub-frame 596, shown partially cutaway in FIG. 54 in order to more clearly show the apparatus beneath it, 40 is rectangular in shape and is driven in a reciprocating linear motion by cam follower 597 attached to the edge of sub-frame 596. The reciprocating linear motion of sub-frame 596 is preferably effected in an at least sub-

stantially horizontal plane although it can be carried out in a plane inclined to the horizontal reference at an angle in the range of about 1° to about 45°, more preferably in the range of about 1° to about 10°. Such an inclined plane would generally extend upwardly from the top face of rail 594 over the top surface of conveyor 46 in order to permit the container 50 to clear the rail 594. Cam follower 597 rides in groove 598 of cam wheel 599 as cam wheel 599 is rotated by the main drive shaft 600 and cam drive shaft 601. Sub-frame 596 is supported on brackets 602 (FIG. 56) which are slideable on rods 603 attached to the main frame 595.

Sub-frame 596 has attached to its bottom portion, at each end, a bracket 604, each of which carries two vacuum cup mounts 605. Each vacuum cup mount 605 has connected to it a vacuum cup 606 for contacting the filled and sealed cartons 50 at the adjacent transfer station. Vacuum cups 606 are connected to a suitable source of vacuum 607 through vacuum cup mounts 605, vacuum lines 608, and vacuum valve 609. On its rear edge, sub-frame 596 has an adjustable stop 610 (FIG. 55) which contacts actuating means 611 of vacuum valve 609 at one end of the reciprocating stroke of sub-frame 596.

The delivery conveyor 46 located at a right angle to the center line of the packaging machine is tangent to the curved paths of conveyors 17 and is adjacent to both transfer stations 25a and 25b to carry filled cartons away from transfer mechanism 25. Guide rails 612 extend above the surface of delivery conveyor 46 to guard against containers being improperly positioned on, or falling from, conveyor 46 and are attached to support bar 613 (FIG. 55) which is in turn attached to the main frame 595 of the filling and sealing machine. The top of conveyor 46 is preferably slightly lower than the top of flat 594 to permit container 50 to be moved laterally from transfer stations 25a and 25b without contacting the surface of conveyor 46.

FIG. 55 is a simplified elevational view of transfer station 25b with the sub-frame 596 in its extreme forward position. In this position, vacuum cups 606 are in contact with the side of the container 50 at transfer station 25b, and adjustable stop 610 has been released from contact with actuating means 611 of vacuum valve 609, thus causing vacuum to be applied through vacuum lines 608 and vacuum cup mounts 605 to vacuum cups 606.

FIG. 56 illustrates the connection of bracket 604 and bracket 602 to sub-frame 596. Rod 603 is fitted to the hole in bracket 602 in such a way as to provide both support for sub-frame 596 and a guide for the reciprocating motion of sub-frame 596. Vacuum cup mounts 605 are attached to bracket 604 so that vacuum cups 606 are preferably located one above the other and spaced to permit gripping of a filled container 50 near the top and near the bottom of a flat, vertical side of the container.

In operation, filled and sealed cartons are delivered by the respective conveyors 17 to transfer stations 25a and 25b simultaneously. The indexing motion of the conveyor 17 stops the conveyor pockets 45 at the transfer stations 25a and 25b. During the interval that the conveyors 17 are stopped, cam wheel 599 makes one complete revolution. At the start of the rotation of cam wheel 599, the sub-frame 596 is in the rear position with the stop 610 contacting actuating means 611 of vacuum 609, thereby interrupting the vacuum sup-

ply to vacuum cups 606. As cam wheel 599 rotates, the sub-frame 596 moves forward, releasing actuating means 611 and activating vacuum valve 609, thereby applying a vacuum to the vacuum cups 606 through vacuum line 608. As the sub-frame 596 reaches the end of its forward motion, the vacuum cups 606 contact and grip the sides of filled cartons 50 located at transfer stations 25a and 25b. As the sub-frame 596 begins its backward motion, vacuum cups 606 carry the respective cartons 50 from the transfer stations 25a and 25b backward to a position above the delivery conveyor 46. At this point the bottoms of the cartons 50 are slightly above the surface of the delivery conveyor 46. As the sub-frame 596 reaches the end of its backward movement, stop 610 contacts actuating means 611 of vacuum valve 609 and interrupts the supply of vacuum to vacuum cups 606 allowing the filled cartons 50 from transfer stations 25a and 25b to drop onto delivery conveyor 46 and be carried away. Conveyors 17 then advance two more filled and sealed cartons to transfer stations 25a and 25b, and the cycle removing the carton 50 from transfer stations 25a and 25b to delivery conveyor 46 is repeated.

Although the transfer mechanism has been illustrated in a preferred embodiment employing two vacuum cups to grip each carton transferred with a substantially air-tight seal, one vacuum cup gripping each carton can be employed or more than two vacuum cups to grip each carton can be utilized.

Reasonable variations and modifications are possible within the scope of the foregoing disclosure and the appended claims to the invention.

That which is claimed is:

1. A machine for forming a tubular carton from a generally rectangular flat sidewall blank having thermoplastic coatings on the upper and lower surfaces thereof and having first and second side margins and top and bottom margins, which comprises a forming mandrel, means for wrapping said sidewall blank around said forming mandrel to overlap said first and second side margins thereof, a conveying means having a conveyor run on which said blank is to be transported through a heating station to said forming mandrel, said conveying means having means for engaging a blank deposited on said conveyor run, a supply magazine means for containing a plurality of said blanks, transfer means for successively withdrawing individual blanks from said supply magazine means and for depositing each thus withdrawn individual blank on said conveyor run, holding means for maintaining the position to the thus deposited blank on said conveyor run until after the thus deposited blank is contacted by said means for engaging, means for actuating said holding means to contact said thus withdrawn individual blank as the blank is being deposited on said conveyor run, means for periodically activating said conveying means, means for actuating said transfer means during the time said conveying means is inactive, a first conduit means positioned in said heating station at least generally parallel to and spaced generally upwardly from the location which would be occupied by the upper surface of the first side margin of the blank in said heating station, said first conduit means having orifices therein spaced along the length thereof and directed at the location which would be occupied by said upper surface of said first side margin of the blank in said heating station, a second conduit means positioned in said heating station

at least generally parallel to and spaced generally downwardly from the location which would be occupied by the lower surface of the second side margin of the blank in said heating station, said second conduit means having orifices therein spaced along the length thereof and directed at the location which would be occupied by the lower surface of said second side margin of the blank in said heating station, and means for supplying a hot gas to said first and second conduit means.

2. A machine in accordance with claim 1 further comprising means for mounting said supply magazine means over said conveyor run; and wherein said transfer means comprises at least one suction cup, means mounted beneath said conveyor run adapted to move said at least one suction cup upwardly through said conveyor run into engaging contact with the bottom one of said blanks in said supply magazine means and then to return said at least one suction cup downwardly through said conveyor run to deposit the withdrawn blank on said conveyor run, and means for maintaining a vacuum in said at least one suction cup from the time said at least one suction cup contacts the bottom blank in said supply magazine means to the time the withdrawn blank is deposited on said conveyor run; wherein the first and second side margins of the blanks in said supply magazine means extend generally in the direction of movement of said conveyor run; and wherein said holding means comprises first and second hold-down means, said first hold-down means being positioned to engage the upper surface of the first side margin of the blank being deposited on said conveyor run and said second hold-down means being positioned to engage the upper surface of the second side margin of the blank being deposited on said conveyor run.

3. A machine in accordance with claim 2 wherein said means for actuating said holding means comprises a first pair of horizontally positioned shafts, means for mounting said first hold-down means on one of said first pair of shafts for rotation therewith, means for mounting said second hold-down means on the other of said first pair of shafts for rotation therewith, a second pair of vertically positioned shafts, first and second vertically positioned sleeves, one of said second pair of shafts being positioned within and extending above said first sleeve, the other of said second pair of shafts being positioned within and extending above said second sleeve, each of said second pair of shafts having a clevis block secured to the upper end thereof and being provided with a spring positioned between and under compression by the respective clevis block and the respective sleeve, each of said second pair of shafts having a vertically extending slot therein, each of said sleeves having a pin therein extending through the slot of the associated one of said second pair of shafts to permit relative motion between each of said sleeves and the associated vertical shaft to the extent of the slot in the associated vertical shaft, means responsive to the generally vertical movement of one of said clevis blocks for rotating said one of said first pair of shafts, means responsive to the generally vertical movement of the other of said clevis blocks for rotating said other of said first pair of shafts, and means for moving said first and second sleeves at least generally vertically responsive to the vertical movement of said at least one suction cup.

4. A machine in accordance with claim 3 further comprising third conduit means positioned in said heat-

ing station at least generally parallel to and spaced from the location which would be occupied by the upper surface of the bottom margin of the blank in said heating station, said third conduit means having orifices therein

5 spaced along the length thereof and directed at the location which would be occupied by said upper surface of said bottom margin of the blank in said heating station, and means for supplying hot gas to said third conduit means, the initial orifice in one of said first and 10 second conduit means being adjacent to the location which would be occupied by the top margin of the blank in said heating station and the initial orifice of the other of said first and second conduits being adjacent to the location which would be occupied by the bottom 15 margin of the blank in said heating station.

5. A machine in accordance with claim 1 wherein at least a major portion of the blank contacting surface of said mandrel is coated with a coating composition comprising a normally solid poly(arylene sulfide).

6. A machine in accordance with claim 1 wherein said holding means comprises first and second hold-down means, said first hold-down means being positioned to engage the upper surface of the first side margin of the blank being deposited on said conveyor run and said second hold-down means being positioned to engage the upper surface of the second side margin of the blank being deposited on said conveyor run; and wherein said means for actuating said holding means comprising a first pair of horizontally positioned shafts, 20 means for mounting said first hold-down means on one of said first pair of shafts for rotation therewith, means for mounting said second hold-down means on the other of said first pair of shafts for rotation therewith, a second pair of vertically positioned shafts, means for 25 moving said second pair of shafts at least generally vertically responsive to the vertical movement of said transfer means, means responsive to the generally vertical movement of one of said second pair of shafts for rotating said one of said first pair of shafts, and means 30 responsive to the generally vertical movement of the other of said second pair of shafts for rotating said other of said first pair of shafts.

7. A machine in accordance with claim 1 further comprising third conduit means positioned in said heating station at least generally parallel to and spaced from the location which would be occupied by one surface of the bottom margin of the blank in said heating station, said third conduit means having orifices therein spaced along the length thereof and directed at the location which would be occupied by said one surface of said bottom margin of the blank in said heating station, and means for supplying hot gas to said third conduit means.

8. A machine in accordance with claim 7 wherein the initial orifice in one of said first and second conduit means is adjacent to the location which would be occupied by the top margin of the blank in said heating station and the initial orifice of the other of said first and second conduits is adjacent to the location which would be occupied by the bottom margin of the blank in said heating station.

9. A machine in accordance with claim 8 wherein at least a major portion of the blank contacting surface of said mandrel is coated with a coating composition comprising a normally solid poly(arylene sulfide).

10. A machine in accordance with claim 7 further comprising a fourth conduit means positioned between

said supply magazine means and said heating station, said fourth conduit means having a series of orifices therein spaced along the length thereof to form an air curtain between said supply magazine means and said heating station, and means for providing cool gas to said fourth conduit means.

11. A machine in accordance with claim 1 further comprising a third conduit means positioned between said supply magazine means and said heating station, said third conduit means having a series of orifices therein spaced along the length thereof to form an air curtain between said supply magazine means and said heating station, and means for providing cool gas to said third conduit means.

12. A machine in accordance with claim 11 wherein said means for providing cool gas to said third conduit means is actuated only when the machine is actuated and said conveying means is deactivated.

13. A machine in accordance with claim 4 wherein at least a major portion of the blank contacting surface of said mandrel is coated with a coating composition comprising a normally solid poly(arylene sulfide).

14. A machine for forming a tubular carton from a generally rectangular flat sidewall blank having thermoplastic coatings on the upper and lower surfaces thereof and having first and second side margins and top and bottom margins, which comprises a forming mandrel, means for wrapping said sidewall blank around said forming mandrel to overlap said first and second side margins thereof, a conveying means having a conveyor run on which said blank is to be transported through a heating station to said forming mandrel, a supply magazine means for containing a plurality of said blanks, transfer means for successively withdrawing individual blanks from said supply magazine means and for depositing each thus withdrawn individual blank on said conveyor run, a first conduit means positioned in said heating station at least generally parallel to and spaced generally upwardly from the location which would be occupied by the upper surface of the first side margin of the blank in said heating station, said first conduit means having orifices therein spaced along the length thereof and directed at the location which would be occupied by said upper surface of said first side margin of the blank in said heating station, a second conduit means positioned in said heating station at least generally parallel to and spaced generally downwardly from the location which would be occupied by the lower surface of the second side margin of the blank in said heating station, said second conduit means having orifices therein spaced along the length thereof and directed at the location which would be occupied by the lower surface of said second side margin of the blank in said heating station, means for supplying a hot gas to said first and second conduit means, and at least a major portion of the blank contacting surface of said mandrel being coated with a coating composition comprising a normally solid poly(arylene sulfide).

15. A machine in accordance with claim 14 wherein said mandrel comprises a hollow aluminum mandrel body and a steel end cap positioned on one end of said mandrel body, all of the blank contacting surfaces of said mandrel body being coated with a continuous layer of said coating composition.

16. A machine in accordance with claim 15 further comprising a turret having a plurality of said mandrels positioned thereon with the elongated axis of each

mandrel being in a plane perpendicular to the axis of rotation of said turret and extending radially with respect to said axis of rotation, and means for rotating said turret.

17. A machine in accordance with claim 16 wherein said conveying means has means for engaging a blank deposited on said conveyor run; and further comprising holding means for maintaining the position of the blank being deposited on said conveyor run until after the thus deposited blank is contacted by said means for engaging, means for actuating said holding means to contact the blank withdrawn from said supply magazine means as the withdrawn blank is being deposited on said conveyor run.

18. A machine in accordance with claim 17 wherein said coating composition comprises a normally solid poly(arylene sulfide), from about 0.5 to about 100 percent by weight titanium dioxide, based on the weight of poly(arylene sulfide), and from about 0.5 to about 75 percent by weight fluorocarbon polymer, based on the weight of poly(arylene sulfide).

19. Apparatus in accordance with claim 6 further comprising a third conduit means positioned between said supply magazine means and said heating station, said third conduit means having a series of orifices therein spaced along the length thereof to form an air curtain between said supply magazine means and said heating station, and means for providing cool gas to said third conduit means.

20. A machine in accordance with claim 9 further comprising a conveyor having a plurality of carton holders, each carton holder having first and second side walls connected by a back wall to form a generally U-shaped pocket, said conveyor having a transfer station, at least one filling station, a heating station, and at least one sealing station; an upstream guide wall means and a downstream guide wall means positioned adjacent said transfer station to guide a carton into the carton holder in said transfer station, means for withdrawing a carton from a mandrel on said turret and transferring the thus withdrawn carton between said upstream guide wall means and said downstream guide wall means into said carton holder in said transfer station, a positioning element pivotably mounted adjacent the edge of said downstream guide wall means closest to said conveyor whereby the carton inserted into the article holder in said transfer station is in contact with said positioning element as said conveyor commences to move said carton and its associated carton holder from said transfer station, and means for resiliently biasing said positioning element to force the carton into the desired position in the carton holder and to maintain the desired position and then to permit the carton and holder to be moved out of said transfer station by the conveyor, and means for intermittently driving said conveyor.

21. A machine in accordance with claim 20 wherein said means for intermittently driving said conveyor comprises a drive shaft, a first ratchet mounted on said drive shaft and secured thereto for rotation therewith and having teeth extending in a first direction, a second ratchet mounted on said drive shaft and secured thereto for rotation therewith and having teeth extending in the direction opposite to said first direction, at least one ratchet drive pawl, pawl support means for mounting said at least one ratchet drive pawl and adapted for rotation about the elongated axis of said

drive shaft, means for resiliently urging said at least one ratchet drive pawl into engagement with the teeth of said first ratchet during the forward rotation of said pawl support means about the said elongated axis to rotate said first and second ratchets and said drive shaft during the forward rotation of said pawl support means, reciprocating means for driving said pawl support means forward and then backward in oscillatory rotative motion about said elongated axis, a pivotably mounted brake arm adapted to be rotated into contact with a tooth of said second ratchet during the forward rotation of said pawl support means, a striker arm resiliently mounted on said pawl support means and adapted to engage said brake arm and pivot said brake arm into contact with a tooth of said second ratchet during the final portion of the forward rotation of said pawl support means.

22. A machine in accordance with claim 21 wherein said resiliently mounted striker arm is adapted to apply pressure to a tooth of said second ratchet to cause the driven tooth of said first ratchet to move back into contact with said ratchet drive pawl before the commencement of the backward motion of said pawl support means in the event that said first and second ratchets and said drive shaft continued to rotate after the end of the forward motion of said pawl support means.

23. Apparatus in accordance with claim 22 further comprising an annular drive plate for driving said conveyor, said drive plate being positioned about said drive shaft for rotative movement free of the movement of said drive shaft, a clutch plate mounted on said drive shaft and secured thereto for rotation therewith, one of said drive plate and said clutch plate being provided with depressions in the surface thereof facing the other of said drive plate and said clutch plate, said other of said drive plate and said clutch plate being provided with pins for engaging said depressions, and means for resiliently mounting said pins so that a jamming of said conveyor will cause said pins to disengage from said depressions, thereby permitting said drive shaft to be indexed without rotating said drive plate, said depressions being uniformly spaced at intervals corresponding to the degree of rotation of said drive shaft for each forward movement of said pawl support means so that said pins will reengage said depressions only when said drive plate is in proper relationship with said drive shaft.

24. A machine in accordance with claim 23 for forming, filling and sealing gable top cartons formed from said blanks, each of said blanks having score lines therein defining a gable top forming structure; means at said at least one filling station for introducing into each of said cartons the product to be packaged; means for braking the score lines in the gable top forming structure of each carton to form six ridge panels defining a six sided opening in each carton; and means located at said heating station for heating the six ridge panels, comprising a support base, means attached to a central portion of the lower surface of said support base to define a central plenum chamber having a continuous outer perforated wall which has six sections corresponding to the six sides of said opening in said carton, means attached to the peripheral portion of the lower surface of said support base to define an outer annular plenum chamber having a continuous inner perforated wall with six sections corresponding to the six sides of said opening, said outer wall of said central plenum chamber and said inner wall of said outer

plenum chamber forming an annular space adapted to receive therein the ridge panels of a prebroken gable top structure of a filled carton without contact between the carton and the heating head, means for introducing

5 heated gas into said central plenum chamber and into said outer plenum chamber, said outer wall of said central plenum chamber having perforations therethrough spaced at intervals along the length of each of the six sections thereof for directing jets of heated gas at the 10 inner surface of each of the six ridge panels of the carton being heated, said outer wall of said central plenum chamber being inclined downwardly from said support base and outwardly away from the vertical axis of the carton being heated so that said jets of heated gas strike 15 the inner surfaces of said ridge panels at acute angles and are deflected upwardly out of the carton; and means at said at least one sealing station for applying pressure to the thus heated ridge panels of each carton to seal said opening.

25. A machine in accordance with claim 24 wherein said conveyor has a carton removal station, and further comprising a continuously actuated conveyor having a carton receiving station located thereon; and carton transfer means for moving a carton from said carton removal station to said carton receiving station, said carton transfer means comprising one or more suction cups capable of producing a substantially air-tight seal with the surface of the carton to be transferred, vacuum supply means operably connected to said one or more suction cups, reciprocating means for moving said one or more suction cups between a first position in contact with the surface of a carton located in said carton removal station and a second position in contact 30 with the surface of a carton located in said carton receiving station, and vacuum control means interposed between said vacuum supply means and said one or more suction cups to apply a vacuum to said one or more suction cups while said reciprocating means is in 35 said first position and traveling between said first position and said second position and to interrupt the vacuum supply to said one or more suction cups while said reciprocating means is in said second position.

40. Apparatus in accordance with claim 14 wherein the initial orifice in one of said first and second conduit means is adjacent the location which would be occupied by the top margin of the blank in said heating station and the initial orifice of the other of said first and second conduits is adjacent the location which would 45 be occupied by the bottom margin of the blank in said heating station.

45. Apparatus in accordance with claim 14 wherein the initial orifice in one of said first and second conduit means is adjacent the location which would be occupied by the top margin of the blank in said heating station and the initial orifice of the other of said first and second conduits is adjacent the location which would 50 be occupied by the bottom margin of the blank in said heating station.

55. Apparatus in accordance with claim 26 further comprising third conduit means positioned in said heating station at least generally parallel to and spaced from the location which would be occupied by one surface of the bottom margin of the blank in said heating station, said third conduit means having orifices therein spaced along the length thereof and directed at the location which would be occupied by said one surface of said bottom margin, and means for supplying hot gas to said third conduit means.

60. Apparatus in accordance with claim 27 wherein said third conduit means has a partition therein at about the midpoint of the width of the blank in the heating station to form separate plenum chambers, and wherein said means for supplying hot gas to said third conduit means comprises means for supplying hot gas

to each of said plenum chambers at locations remote from said partition.

29. Apparatus in accordance with claim 16 further comprising third conduit means positioned in said heating station at least generally parallel to and spaced from the location which would be occupied by one surface of the bottom margin of the blank in said heating station, said third conduit means having orifices therein spaced along the length thereof and directed at the location which would be occupied by said one surface of said bottom margin of the blank in said heating station, and means for supplying hot gas to said third conduit means.

30. Apparatus in accordance with claim 29 further comprising means for periodically actuating the conveyor means for transporting the individual blanks through said heating station to index a blank into position with respect to said first, second and third conduit means, and wherein the initial orifice in one of said first and second conduit means is adjacent the location which would be occupied by the top margin of the blank in said heating station and the initial orifice of the other of said first and second conduits is adjacent the location which would be occupied by the bottom margin of the blank in said heating station.

31. Apparatus in accordance with claim 30 wherein said third conduit means has a partition therein at about the midpoint of the width of the blank in the heating station to form separate plenum chambers, and wherein said means for supplying hot gas to said third conduit means comprises means for supplying hot gas to each of said plenum chambers at locations remote from said partition.

32. Apparatus in accordance with claim 30 further comprising a fourth conduit means positioned between said supply magazine means and said heating station, said fourth conduit means having a series of orifices therein spaced along the length thereof to form an air curtain between said supply magazine means and said heating station, and means for providing cool gas to said fourth conduit means.

33. Apparatus in accordance with claim 32 wherein said means for providing cool gas to said fourth conduit means is actuated only when the machine is actuated and said conveying means is deactivated.

34. A machine in accordance with claim 14 wherein said coating composition comprises a normally solid poly(arylene sulfide), from about 0.5 to about 100 percent by weight titanium dioxide, based on the weight of poly(arylene sulfide), and from about 0.5 to about 75 percent by weight fluorocarbon polymer, based on the weight of poly(arylene sulfide).

35. A machine in accordance with claim 7 wherein said coating composition comprises a normally solid poly(arylene sulfide), from about 0.5 to about 100 percent by weight titanium dioxide, based on the weight of poly(arylene sulfide), and from about 0.5 to about 75 percent by weight fluorocarbon polymer, based on the weight of poly(arylene sulfide).

36. A machine in accordance with claim 8 wherein said coating composition comprises a normally solid poly(arylene sulfide), from about 0.5 to about 100 percent by weight titanium dioxide, based on the weight of poly(arylene sulfide), and from about 0.5 to about 75 percent by weight fluorocarbon polymer, based on the weight of poly(arylene sulfide).

37. A machine in accordance with claim 6 further comprising third conduit means positioned in said heating station at least generally parallel to and spaced from the location which would be occupied by one surface of the bottom margin of the blank in said heating station, said third conduit means having orifices therein spaced along the length thereof and directed at the location which would be occupied by said one surface of said bottom margin, and means for supplying hot gas to said third conduit means; and further comprising means for periodically actuating the conveyor means for transporting the individual blanks through said heating station to index a blank into position with respect to said first, second and third conduit means.

38. A machine in accordance with claim 37 further comprising a fourth conduit means positioned between said supply magazine means and said heating station, said fourth conduit means having a series of orifices therein spaced along the length thereof to form an air curtain between said supply magazine means and said heating station, and means for providing cool gas to said fourth conduit means.

39. A machine in accordance with claim 38 wherein said means for providing cool gas to said fourth conduit means is actuated only when the machine is actuated and said conveying means is deactivated.

40. A machine in accordance with claim 8 further comprising a conveyor having a plurality of carton holders, each carton holder having first and second side walls connected by a back wall to form a generally U shaped pocket, said conveyor having a transfer station, at least one filling station, a heating station, and at least one sealing station; means for withdrawing a carton from a mandrel on said turret and transferring the thus withdrawn carton into said carton holder in said transfer station, and means for intermittently driving said conveyor.

41. A machine in accordance with claim 40 further comprising an upstream guide wall means and a downstream guide wall means positioned adjacent said transfer station to guide a carton into the carton holder in said transfer station, a positioning element pivotably mounted adjacent the edge of said downstream guide wall means closest to said conveyor whereby the carton inserted into the article holder in said transfer station is in contact with said positioning element as said conveyor commences to move said carton and its associated carton holder from said transfer station, and means for resiliently biasing said positioning element to force the carton into the desired position in the carton holder and to maintain the desired position and then to permit the carton and holder to be moved out of said transfer station by the conveyor.

42. A machine in accordance with claim 40 wherein said means for intermittently driving said conveyor comprises a drive shaft, a first ratchet mounted on said drive shaft and secured thereto for rotation therewith and having teeth extending in a first direction, a second ratchet mounted on said drive shaft and secured thereto for rotation therewith and having teeth extending in the direction opposite to said first direction, at least one ratchet drive pawl, pawl support means for mounting said at least one ratchet drive pawl and adapted for rotation about the elongated axis of said drive shaft, means for resiliently urging said at least one ratchet drive pawl into engagement with the teeth of said first ratchet during the forward rotation of said

pawl support means about the said elongated axis to rotate said first and second ratchets and said drive shaft during the forward rotation of said pawl support means, reciprocating means for driving said pawl support means forward and then backward in oscillatory rotative motion about said elongated axis, a pivotably mounted brake arm adapted to be rotated into contact with a tooth of said second ratchet during the forward rotation of said pawl support means, a striker arm resiliently mounted on said pawl support means and adapted to engage said brake arm and pivot said brake arm into contact with a tooth of said second ratchet during the final portion of the forward rotation of said pawl support means.

43. A machine in accordance with claim 42 wherein said resiliently mounted striker arm is adapted to apply pressure to a tooth of said second ratchet to cause the driven tooth of said first ratchet to move back into contact with said ratchet drive pawl before the commencement of the backward motion of said pawl support means in the event that said first and second ratchets and said drive shaft continued to rotate after the end of the forward motion of said pawl support means.

44. A machine in accordance with claim 40 for forming, filling and sealing gable top cartons from said blanks, each of said blanks having score lines therein defining a gable top forming structure; means at said at least one filling station for introducing into each of said cartons the product to be packaged; means for breaking the score lines in the gable top forming structure of each carton to form six ridge panels defining a six sided opening in each carton; and means located at said heating station for heating the six ridge panels, comprising a support base, means attached to a central portion of the lower surface of said support base to define a central plenum chamber having a continuous outer perforated wall which has six sections corresponding to the six sides of said opening in said carton, means attached to the peripheral portion of the lower surface of said support base to define an outer annular plenum chamber having a continuous inner perforated wall with six sections corresponding to the six sides of said opening, said outer wall of said central plenum chamber and said inner wall of said outer plenum chamber forming an an-

nular space adapted to receive therein the ridge panels of a prebroken gable top structure of a filled carton without contact between the carton and the heating head, means for introducing heated gas into said central plenum chamber and into said outer plenum chamber, said outer wall of said central plenum chamber having perforations therethrough spaced at intervals along the length of each of the six sections thereof for directing jets of heated gas at the inner surface of each of the six ridge panels of the carton being heated, said outer wall of said central plenum chamber being inclined downwardly from said support base and outwardly away from the vertical axis of the carton being heated so that said jets of heated gas strike the inner surfaces of said ridge panels at acute angles and are deflected upwardly out of the carton; and means at said at least one sealing station for applying pressure to the thus heated ridge panels of each carton to seal said opening.

45. A machine in accordance with claim 40 wherein said conveyor has a carton removal station, and further comprising a continuously actuated conveyor having a carton receiving station located thereon; and carton transfer means for moving a carton from said carton removal station to said carton receiving station, said carton transfer means comprising one or more suction cups capable of producing a substantially air-tight seal with the surface of the carton to be transferred, vacuum supply means operably connected to said one or more suction cups, reciprocating means for moving said one or more suction cups between a first position in contact with the surface of a carton located in said carton removal station and a second position in contact with the surface of a carton located in said carton receiving station, and vacuum control means interposed between said vacuum supply means and said one or more suction cups to apply a vacuum to said one or more suction cups while said reciprocating means is in said first position and traveling between said first position and said second position and to interrupt the vacuum supply to said one or more suction cups while said reciprocating means is in said second position.

UNITED STATES PATENT AND TRADEMARK OFFICE
CERTIFICATE OF CORRECTION

PATENT NO. : 3,890,765

DATED : June 24, 1975

INVENTOR(S) : Silvio T. Farfaglia; Leslie O. Coburn; Robert G. Halpin;
Ronald E. Bock

It is certified that error appears in the above-identified patent and that said Letters Patent
are hereby corrected as shown below:

Column 32, line 50, delete "to" and insert -- of --.
Column 37, line 53, delete "braking" and insert -- breaking --.
